UNITED STATES PATENT OFFICE

DAVID L. LINDQUIST, OF HARTSDALE, NEW YORK, EDWARD L. DUNN, OF MONTCLAIR, NEW JERSEY, AND DAVID C. LARSON, OF YONKERS, NEW YORK, ASSIGNEES TO OTIS ELEVATOR COMPANY, OF JERSEY CITY, NEW JERSEY, A CORPORATION OF NEW JERSEY

ELEVATOR SYSTEM

Original application filed February 3, 1925, Serial No. 6,561. Divided and this application filed October 9, 1925, Serial No. 61,474. Renewed January 8, 1930.

This invention relates to elevator systems.

This application is a division of application Serial No. 6561, filed February 3, 1925.

The principal object of the invention is to provide an elevator system wherein the maximum of service with greatly increased efficiency of operation may be obtained with a single elevator car or with a bank of elevator cars.

One feature of the invention is to have the starting of an elevator car under the control of an operator, with the stopping of the car, to pick up prospective passengers, under the control of the passengers themselves, without further act of the operator.

Another feature is to have the car stop to discharge passengers at floors selected by the operator, the stopping operation being automatic.

A third feature involves the stopping of only one car of a bank of elevators at a landing in response to the pushing of a button by a prospective passenger.

A fourth feature resides in automatically signalling the approach of a car about to stop at a landing, when the stop is caused by a prospective passenger, without signalling the approach when the stop is caused by the operator.

Other features and advantages will become apparent from the following description, taken in connection with the accompanying drawings wherein one embodiment of the invention is illustrated and in which:

Figure 1 is a simplified schematic representation of two elevators, as illustrative of a group of elevators in a bank;

Figure 2 is a front elevation of the car operating box;

30 Figure 39 is a fragmental detail of the brake operated switch.

For a general understanding of the invention, reference may be had to Figure 1 wherein various parts of the system are indicated by legend. Referring particularly to the left hand half of the figure wherein the parts for one elevator, hereinafter to be known as elevator No. 1, are represented, the car is driven by the main motor controlled by various electromagnetic switches mounted on the control panel. The starting of the car is under control of an operator in the car, a starting switch, preferably arranged in the car operating box, being provided for this purpose. The starting switch is not employed to determine the direction of travel of the car, it being preferred to arrange a separate switch for this purpose. This "director switch" is reversed by the "director switch" hatchway cams at the terminal floors, being preferably mounted on the top of the car for convenience of operation.

50 Normally, once the car has started, it will continue to run until stopped by the selector machine. The selector machine is driven preferably by means of two steel tapes attached to the car. One tape extends from the top of the car to an overhead sheave around which it is wound in a manner similar to the winding of a measuring tape. The other tape extends from the bottom of the car around a tension sheave and then up to a second overhead sheave upon which it is similarly but oppositely wound. The overhead sheaves cause the operation of the selector machine, one tape winding up as the other is unwound in the driving operation. This silent drive is as positive

as a sprocket chain and is unaffected by sliding or stretching ropes.

Push buttons are provided in the car, preferably arranged in the car operating box, for causing the selector machine to stop the car at the intermediate floors. A wheel or lever is also provided in the car for reversing the "director switch" by hand. In the event of extra floors, the hatchway cams are arranged to permit the return of the "director switch" with the car stopped at the terminal floor and to again reverse the switch as the extra floor is reached.

A leveling switch and leveling cams may be provided for causing the car to be brought to the landing in the event that an exact stop has not been made. An auxiliary motor also may be provided in the event that it is not desired to effect the leveling operation with the main motor.

The other elevators in a group, as indicated by elevator No. 2, are arranged in an identical manner except that no provision may be made for extra floor runs. "Up" and "down" push buttons, common to all the elevators, are arranged at the intermediate floors. These push buttons, to be known as hall buttons, are for causing the selector machines to effect the operation of signals upon the approach of their respective cars and to stop the cars at the landings. The hall buttons are preferably arranged to act through floor stop switches and floor signal switches mounted on the "stop and signal" panel.

Each car may be provided with an annunciator for indicating the various calls to the operator, in which event buttons may be provided at the top and bottom floors for causing the operation of the annunciator for those floors. A separate annunciator and a position indicator may be provided on the dispatcher panel for the convenience of the dispatcher in directing the various cars of the group. Signal switches may be arranged on the dispatcher panel for operating signals in the various cars. Non-stop cut-out switches also may be arranged on this panel for insuring the response of the cars to calls from the various floors.

The system will be described as applied to a ten floor installation with extra top and bottom floors. It is to be understood, however, that the system may be arranged for any number of floors, ten being chosen merely for purpose of description. The car operating box, "director switch", selector machine and floor switches will be described for elevator No. 1, it being understood that these devices are identical for all the elevators of a group.

Referring now to Figures 2 to 7 inclusive, the details of the preferred form of car operating box will be described. This box, designated as a whole by numeral 600, is separated into an upper and lower compartment, the upper compartment 601 for the

magnetic push button apparatus and the lower compartment 602 for various control switches employed in the present system. The compartments may be joined in any suitable manner, for example by means of bolts as illustrated.

The lower compartment comprises a casing 603 and cover plate 604 within which the control switches are enclosed. These switches comprise safety switch 44, slow speed switch 122, non-stop switch 605, auxiliary motor switch 606, emergency cut-out switch 526, light switch 608 and starting switch 610. The safety, slow speed and non-stop switches are arranged in a group and mounted in an insulating box 611. The switches are separated by insulating partitions 612. The auxiliary motor, emergency cut-out and light switches are similarly arranged in insulating box 613. The boxes 611 and 613 are secured to the casing 603.

Safety switch 44, slow speed switch 122, non-stop switch 605 and light switch 608 may be of any suitable construction, being illustrated as double pole, single throw knife switches. Each switch is provided with an operating lever 614. Apertures 615, through which these levers extend, are provided in the cover plate 604. The safety switch, slow speed switch and light switch are provided with toggle arrangements (not shown), of any well known construction, for maintaining the switches in either closed or open positions. As it is desired to respond to all calls from the various floors except under certain conditions, as will be explained later, the non-stop switch is spring-biased to closed position. The two blades of the safety switch, slow speed switch and light switch are electrically connected. The blades of the non-stop switch, however, are unconnected, forming in effect two separate switches 281 and 323 for the hall stop and signal circuits respectively. The light switch is used for completing the circuit to the lamp in the car, indicated in Figure 1. The purpose of the other switches will be evident from the description of operation hereinafter set forth.

Auxiliary motor switch 606 in effect forms two switches 518 and 519. The switches are arranged in any suitable manner for connection to a common feed, such connection being diagrammatically represented in Figure 32. The switches are biased by means of a spring (not shown) tending to maintain them in open position. The operating lever 614 for the switches extends through an additional aperture 615 provided in cover plate 604.

The emergency cut-out switch 526 is a double pole switch, spring-biased to open position. The switch is mounted behind a glass plate 616 arranged in an aperture 617 in cover plate 604. The glass plate 616 is held against a seat, formed around the aperture

617, by means of a retainer 618. The retainer is formed with an aperture 619 for supporting the switch operating button 620. In operation, the glass plate must be broken before the switch can be closed.

Pairs of starting switch contacts 77, 88, 92 and 138 are mounted on a panel 621 secured to the casing 603. Contact bars 624 and 625, for bridging the pairs of contacts, are mounted on a segment 622 of insulating material. The segment 622 is carried by a segmental support 623, being secured thereto as by means of screws in the manner illustrated. Support 623 is pivotally mounted on a spindle 626 secured in a boss 627 formed on the base of casing 603. A positioning collar 628 is pinned to the spindle between the sides of support 623. A centering roller 629 is pivotally mounted between the sides of support 623 and is arranged to cooperate with centering arms 630 and 631 to return the starting switch to "off" or "neutral" position. These arms are pivotally mounted on the base of the casing by means of pins 632 and are forced against limit stops 633 by means of a centering spring 634. The stops 633 are arranged so that the centering arms cannot return the starting switch beyond the "neutral" position. Spring 634, however, will yield and permit the starting switch to be moved into its operative or contact bridging positions.

Casing cover 604 is provided with another aperture 635 for receiving the segmental support hub 636. Starting switch lever 637 is secured to the exterior end of the hub. With the starting lever in "neutral" position, a locking pin 638, provided on the lever, extends into an aperture 640 in cover plate 604. Pin 638 may be withdrawn from the aperture by outward movement of the starting switch handle 641, as is well understood in the art. An arcuate boss 642 is formed on cover plate 604 under the end of the starting lever. Stops 643 for the starting lever are arranged at each end of the boss, an intermediate oblique surface being provided at "Close" position. Three operative positions are indicated on the cover plate, namely, "Close", "Start" and "Open". For convenience of description, these positions will be hereinafter referred to as position I, position II and position III respectively.

In operation, as the starting switch is moved to the left, pin 638 will strike against the oblique surface of the boss 642, indicating that position I has been reached. In this position, contact bar 624 will bridge contacts 77 to cause the operation of the gate closing mechanism and contact bar 625 will bridge contacts 92 to cause the preparation of the automatic stop circuits. As the starting switch is moved farther to the left, the starting lever 637 will strike stop 643, indicating that position II has been reached. In this position,

contact bar 624 will bridge contacts 138 to cause the starting of the car. Upon reverse movement of the starting switch to position III, contact bar 624 will bridge contacts 88 to cause the operation of the gate opening mechanism. Whenever released, the starting switch will be returned to "neutral" position, by the centering mechanism described above, where pin 638 will engage aperture 640 to lock the switch in position. The manner in which the above operations are effected will be described in conjunction with the description of operation of the system as a whole.

The upper or magnetic push button compartment 601 similarly comprises a casing 645 and cover plate 646 within which the magnetic push button apparatus is enclosed. The car button magnet 647 comprises a rectangular coil 67 arranged in elongated iron channels 648 and 649. The magnet is secured at each end to an insulating base 650 as by means of straps 651. The push button switches, 652, 654, 656 and 658 for the second, fourth, sixth and eighth floors respectively, are pivotally mounted on a shaft 660 in such manner that their armatures 661 extend over iron channel 649. Similarly, the push button switches, 653, 655, 657 and 659 for the third, fifth, seventh and ninth floors respectively, are pivotally mounted on shaft 660 but are staggered in relation to the switches 652, 654, 656 and 658. The armatures 661 of switches 653, 655, 657 and 659 extend over iron channel 648. The switches are positioned by means of pins 662 extending through shaft 660. The shaft is secured, as by screws, in supports 663 mounted on an insulating plate 664. Operating buttons 665 for the switches extend through apertures 666 in cover plate 646.

Referring more particularly to Figures 6 and 7, the push button switch details will be described. In Figure 6 two switches are shown, one in open and the other in closed position. The pivoted end of armature 661 is formed with prongs 667 between which pin 662 extends. Stop 670, and a similar stop 668 shown in Figure 5, coextensive with shaft 660, are mounted on insulating plate 664 and are arranged to cooperate with the prongs 667 to limit the upward movement of the armature. The central portion of the armature is formed with an opening 671 across which a pin 672 extends. The pin is secured in the armature at each side of the opening to form a pivot for operating button 665 and contact lever 673. The contact lever 673 extends through a slot 674 formed in operating button 665. A spring 675 extends between the base portion of stop 670 and the inner end of contact lever 673. With the switch in open position, spring 675 acts through contact lever 673 to maintain armature 661 in position with prongs 667 abutting against stop 670. A fixed relation is maintained between lever 673 and armature 661, so long as the switch is in

open position, by the engagement of projection 676 on the lever and the outer end of the armature. A stationary contact 677 is mounted on insulating base 650 in the path of the outer end of the contact lever 673. The stationary contact is provided with a lug 678 adapted for connection with a car stop contact on the selector machine.

In operation, pushing button 665 moves armature 661 and contact lever 673 down against the force of spring 675 until the lever engages stationary contact 677. Then armature 661 moves alone until its outer end engages flange 680 of the iron channel 649, spring 675 acting to maintain the contact lever and contact in engagement. With magnet coil 67 energized, this flange forms one pole of a U-shaped magnet, retaining the switch in closed position. It is preferred to provide an air gap between the armature and the pole formed by flange 681 of iron channel 649, as by shortening the flange, so as to prevent the armature from being held in by residual magnetism. Upon deenergization of magnet coil 67, spring 675 forces the armature into released position with prongs 667 abutting against stop 670. The armature in its movement engages projection 676, separating contact lever 673 and stationary contact 677 to open the switch. It will be seen that as many buttons may be pushed as may be desired, all of which will be retained in closed position in the above described manner so long as the magnet remains energized. Conductors 74 are in the circuit for magnet coil 67 (see Figure 3). A circuit for a push button switch may be traced from conductors 287 to a stationary contact 677, through the switch to shaft 660, support 663, to conductor 105. For convenience of description, these push button switches will be referred to hereinafter as car buttons.

Suitable conduits 684 are provided for the various conductors leading to and from the car operating box. Casings 603 and 645 are preferably formed with lugs 685 for mounting the box in the car. Casing 645 may be provided with a bearing 686 for the "director switch" hand control shaft 687. A hand wheel 688 is pinned to the end of shaft 687 extending into the car, while a sprocket wheel 690 is pinned to the end of the shaft extending to the rear of casing 645 and outside of the car.

Reference may now be had to Figures 8, 9 and 10 which illustrate the details of a preferred form of "director switch." This switch, designated as a whole by numeral 55, is enclosed in a suitable casing 691 and casing cover 692. The casing is provided with brackets 693 and bosses 694 arranged for mounting the switch on the elevator car. Within the casing and secured, as by screws, to a plurality of bosses 695 extending from its base 696 is an annular contact support 123

697. This support has two arcuate slots 698 and 700 in which a plurality of insulating contact bases 701 are adjustably mounted. Suitable spring contacts are secured to these bases, contacts 702 and 72 controlling the circuits for the closing coils of the main "up" and "down" direction switches respectively, and contacts 172, 118, 703 and 508 controlling the circuits for the operating coils of the main accelerating switches. Two feed contacts 71 and 291, similar in construction to the control contacts, are mounted on a support 704 of insulating material. This support, along with an intervening insulating strip 705, is secured to an arcuate boss 706 formed on the contact support 697.

Segment 70, for bridging the above mentioned contacts, comprises an arcuate channel member, formed of an outer flanged portion 707, inner flanged portion 708 and connecting web 710, and a supporting arm 711. The outer flange 707 is arranged for bridging either set of control contacts, 72, 172, and 118 or 702, 703 and 508, while the inner flange 708 is arranged to engage either feed contact 71 or 291. It will be observed that a circuit may thus be completed from either feed contact to the corresponding set of control contacts. Oil wipers 712 and 713 are mounted on insulating support 704 to engage the contact surfaces of flanges 707 and 708 respectively. The supporting arm 711 is mounted on shaft 714 between two insulating plates 715 and 716. A projection 717 on plate 716 extends through an aperture 718 in supporting arm 711 into a recess formed in plate 715. Shaft 714 extends through an inner aperture 720 formed in projection 717 and plate 715. Two other projections 721 are formed on plate 716, being disposed diametrically opposite the projection 717. These latter projections are similarly arranged to extend through apertures in supporting arm 711 into recesses in plate 715. A sleeve 722, arranged on shaft 714, is formed with a flange 723 adjacent to plate 715. Flange 723, plate 715 and projections 721 are apertured to receive studs 724. Nuts 725, on the threaded ends of these studs, clamp the supporting arm 711, plates 715 and 716 and a separating washer 726 against the flange 723. It will be observed that with this arrangement the segment 70 is completely insulated from the flange 723 and shaft 714. A pinion 727 is arranged on shaft 714 in abutting relation with the end of sleeve 722. The pinion, sleeve and segment are held in assembled relation against a shoulder 728, formed on shaft 714, by means of a nut 730 and locking pin 731. A key 732, mounted in a keyway in shaft 714, forms a driving connection between pinion 727 and sleeve 722, while the flange 723 and studs 724 form an operating connection between sleeve 722 and segment 70.

Pinion 727 is driven by means of a segmental gear 733. This gear is mounted on the inner end of a driving shaft 734, being secured thereto as by means of a through bolt 735. Shaft 734 extends through its supporting bearing 736 to the outside of the casing. An operating arm 737 is mounted on the outer end of shaft 734, being similarly secured thereto as by means of another through bolt 735. A roller 738, for engaging the "director switch" hatchway cams, is mounted on the free end of operating arm 737.

Shaft 714 also extends through its supporting bearing 740 to the outside of the casing. A sprocket wheel 741 is mounted on the outer end of shaft 714 beyond the positioning flange 742, being secured as by means of a pin. Sprocket wheel 741 is connected by means of a sprocket chain, as indicated in Figure 1, to sprocket wheel 690 so as to permit operation of the "director switch" from the car.

Two friction plates 743 and 744 are mounted on sleeve 722, the sleeve being square in cross section to form a driving connection. These friction plates cooperate with a stationary annular disc 745 to maintain the "director switch" in the position into which it has been moved. The annular disc 745 is provided with apertured lugs 746. Projections 747, extending from base 696, fit into the apertures of the lugs 746 to hold disc 745 against turning. Friction plate 743, arranged on one side of disc 745, abuts against pinion 727. Friction plate 744 is forced against the other side of the disc, and the disc against friction plate 743, by means of springs 748 mounted on the studs 724. These studs extend into apertures 749 formed in friction plate 744.

Adjustable abutment screws 750, mounted in the sides of the casing 691, determine the limits of movement of the segmental gear 733. These screws form stops to prevent the disengagement of the contacts and bridging segment 70 by extreme movement of the segmental gear in either direction. A suitable opening 751 is provided in the casing 691 for the various conductors leading to and from the "director switch" contacts.

It will be noted, upon reference to Figure 1, that the top floor hatchway cam extends down the hatchway so as almost to engage the "director switch" roller with the car at rest at the ninth floor. The initial engagement of the cam and roller during up car travel will cause the "director switch" to be moved to half speed position. From the point of "director switch" half speed position, the cam slopes gradually to the left up to the point where it moves the switch into "neutral" position. As the control circuits will be broken at this latter point, the slope of the cam is increased in order to move the switch more rapidly into reverse position. It will be further noted that the cam is arranged to

bring the "director switch" to "neutral" position before the top floor is reached in order to allow for the normal coast of the car. This is indicated in the figure by the roller in broken lines for the car at rest at the top floor. The cam at the bottom floor will be identical in construction but reversed so as to move the "director switch" into up position. It is to be understood that the arrangement of the cams may be varied to suit the particular installation.

In operation, assume that the "director switch" is in up position, as indicated by roller 738 and operating arm 737 in broken lines, Figure 8. In this position, flange 707 will bridge control contacts 702, 703 and 508 and flange 708 will engage feed contact 291. As the car approaches the top floor, roller 738, engaging the "director switch" hatchway cam, is carried gradually to the left. As a result of this movement, the segmental gear 733 rotates segment 70 in a clockwise direction. In this manner the circuits controlled by contacts 508, 703 and 702 are broken in the order of the contacts named. As the roller arm is moved into "neutral" position flange 708 moves off feed contact 291. As the roller is carried farther to the left, or into down position, similarly indicated by broken lines, segment 70 is caused to engage contacts 71, 72, 172 and 118, preparing the control circuits for down operation of the car. The friction plates 743 and 744 and disc 745 will permit the movement of the segment 70 but will hold it in this reverse position. Under normal operation, therefore, the segment 70 will remain in down position until similarly but oppositely moved by the hatchway cam at the bottom floor into up position. Again, the friction plates and disc will maintain the switch in this last moved position. Thus the "director switch" normally will be in one of its on positions.

In order to run to an extra floor the "director switch" segment is reversed by means of the handwheel 688. Referring again to Figure 1 and particularly to that part of the figure relating to elevator No. 1, it will be noted that the top floor hatchway cam is arranged to permit the reversal of the "director switch" with the car at rest at the top floor. It is preferred to arrange the cam so as to permit the movement of the "director switch" only to half speed position. The roller, in position for car travel to the extra floor, is indicated in broken lines against the cam. The cam slopes from this point in the same manner as described for the top floor. With the car at rest at the extra floor, the roller, in its reversed position, abuts against the vertical portion of the cam, preventing its further movement at this point. It will be understood that the bottom floor cam will be arranged in a similar manner in the event of an extra bottom floor. When the "director

switch" is moved by hand at the intermediate floors, the extent of movement is determined by abutment screw stops 750.

Reference may now be had to Figures 11 to 25 inclusive which illustrate the various details of a preferred form of selector machine. The selector machine, designated as a whole by numeral 755, comprises a frame formed by a base member 756, four standards 757, 758, 759 and 760 and a top member 761. The standards are secured in sockets formed in bosses 762 on base member 756 and sockets formed in bosses 763 on top member 761.

Referring to Figures 11 to 14 inclusive and particularly to Figure 13, the "selector" slow down and stop switches, 135 and 133 respectively, are mounted on a bracket 64 secured to top member 761 as by bolts. Each switch comprises a pair of stationary contacts 765 and a pair of bridging contacts 766. These contacts may be of any well known construction. Both pairs of stationary contacts are mounted on an insulating contact plate 767 carried by the bracket 764. Each stationary contact is provided with means, such as binding nuts 768, for connecting the switches in the system. Each pair of bridging contacts is mounted in an arm 769 of a contact lever, lever 770 being for the slow-down switch and lever 771 being for the stop switch. Each bridging contact is insulated in any well known manner from its contact lever, the bridge being formed by a flexible conductor 772 connected to the two contacts forming a pair, as illustrated for switch 135 in Figure 12. With the switches in closed positions, each bridging contact is pressed into engagement with its corresponding stationary contact by means of a spring 733. Both contact levers 770 and 771 are pivotally mounted on a pin 774 supported by arms 775 depending from bracket 764. The other arm 776 of each lever is enlarged to form a weight. Each weight acts as a bias tending to move its corresponding switch to closed position. Also pivotally mounted on pin 774, preferably between contact levers 770 and 771, is a bell crank lever 777. The vertical arm of the bell crank lever is formed with diverging prongs 778 and 779 extending into the paths of contact levers 770 and 771 respectively. Abutment screw 781, adjustably mounted in arm 769 of contact lever 770, and abutment screw 782, adjustably mounted in arm 769 of contact lever 771, are arranged for engagement by prongs 778 and 779 respectively during the operation of the switches. The abutment screws are adjusted so that, during the operation of opening the switches, prong 778 will engage screw 781 to open the slow-down switch 135 before prong 779 engages screw 782 to open the stop switch 133. It is to be understood that refinements of adjustments may be made to suit the operating conditions of the particular installation. A socket 783

is pivotally mounted on the horizontal arm 784 of bell crank lever 777. A vertical tube 785 is secured in socket 783, as by means of a pin 786. This tube extends into and is similarly secured in another socket 787. The socket 787 is pivotally mounted on the horizontal arm 788 of a bell crank lever 790. Bell crank lever 790 is pivotally mounted between supports 791 formed on base member 756.

10 The "selector" slow-down and stop switches, 134 and 132 respectively, are identical in construction with slow-down and stop switches 135 and 133 above described, and are similarly mounted on bracket 792. The 15 mechanical construction of the closing mechanism is similar. The horizontal arm 793 of the top bell crank lever 794 and the horizontal arm 795 of the bottom bell crank lever 796, however, extend to the left instead of to 20 the right as do the corresponding arms of bell crank levers 777 and 790. Thus to open switches 135 and 133, tube 785 must move in the up direction as indicated; while to open switches 134 and 132, tube 797, extending 25 between levers 794 and 796, must move in the down direction. The depending arms 798 of the bottom bell crank levers 790 and 796 are joined by means of a cross rod 800. With the 30 cross rod connection, tube 785 must be pulled in the up direction in order to effect the downward movement of tube 797 and, conversely, tube 797 must be pulled in the up direction in order to effect the downward movement of tube 785. Thus the weight of one 35 tube is counterbalanced by the weight of the other. An adjustable screw stop 801 extends through a connecting web 802 for supports 791 into abutting relation with end piece 803 provided on cross rod 800. A 40 weight 804, provided in the lower end of tube 785, serves to unbalance tubes 785 and 797 and acts as a bias tending to maintain the switch opening mechanism in normal position i. e. the position in which end piece 803 45 engages screw stop 801. The screw 801 is so adjusted that with the switch opening mechanism in normal position, the "selector" switches will be free to return to closed positions. A preferred form of mechanism for 50 causing the operation of the switches will now be described.

The base member 756 is formed with a centrally disposed pedestal 805. This pedestal and the boss 762, for standard 757, are arranged to provide bearings 806 and 807 respectively for the selector machine operating shaft 808. The overhead sheaves are secured to the outer end of this shaft as indicated in Figure 1. The pedestal 805 is further arranged to receive a vertical bearing 810 and to support a ball thrust bearing 811 for screw 812. This screw extends vertically into a bearing 813 formed in the top member 761. A beveled gear 814 is secured, as by pin 815, 55 to the lower end of screw 812. Another

bevel gear 816, engaging gear 814 in a driving relation, is secured, as by pin 817 to operating shaft 808. Operative engagement between the bevel gears is maintained by positioning collars 818, secured on shaft 808.

A crosshead, comprising a forked end 820, a nut 821 and frame 822 extending therebetween, is arranged to be driven by screw 812. The forked end 820 engages a vertically extending bar 823 to form a guide for the crosshead. Bar 823 is secured to lugs 824 and 825 formed on base member 756 and top member 761 respectively. A pawl magnet frame 826 is carried by the crosshead nut 821, being secured thereto as by bolts. Frame 826 is 75 arranged to receive the pawl magnet 827. The pawl magnet comprises a coil 114 and central core 828. Non-magnetic plates 829, positioned at each end of the pawl magnet, are secured to the frame 826 as by means of 80 through bolts 830. These plates form a mounting for the pawl magnet, being provided with recesses 831 into which the core 828 extends. The pawl magnet armatures 832 and 833 are pivotally mounted, as by 85 means of pins 834, on arms 835 extending outwardly in opposite directions from the top and bottom of frame 826. The non-magnetic plates 829 further serve as spacing members to prevent armatures 832 and 833 90 from being held in by residual magnetism. Armature 832 extends inwardly from its pivot point to form an arm 836. The end of arm 836 is bifurcated to engage a pin 837 secured in frame 826. A spring 838 is arranged on pin 837 in such manner as to be compressed by arm 836 when the armature is drawn in by pawl magnet 827. Between its end and pivot point, the arm is enlarged to 95 form a weight 839. tion. Each collar 844 may be formed with a U bolt 845 and clamping plate 846 so as to be readily adjustable.

The "selector" stop switches 133 and 132 are arranged in the circuits for the closing coils of the main "up" and "down" direction switches respectively. The "selector" slow-down switches 134 and 135 are arranged in circuits for the operating coil of the first accelerating switch. These circuits are clearly shown in the diagram in Figure 32, reference to which will be had later.

In operation, assume that the car has started in the up direction from the first floor and that the seventh floor car button 657, for example, has been pushed. The selector machine operating shaft 808, driven by means of steel tapes in the manner previously described, will rotate screw 812 through bevel gears 816 and 814. The crosshead nut 821, therefore, will be driven upwardly by screw 812 in proportion to the movement of the elevator car. Pawl magnet coil 114 being energized while the car is running, the pawl magnet armatures 832 and 833 will be in their attracted positions and the pawls 842 and 843 will not engage the stopping collars. As the car reaches the seventh floor stopping zone, due to the fact that the seventh floor car button has been pushed, the pawl magnet coil 114 will be deenergized. The operation of effecting the energization and deenergization of the pawl magnet will be described later. Pawls 842 and 843 are now forced out into their unattracted or stop positions by the armature weights and springs. This is the position illustrated in Figure 13. As the crosshead is driven farther in the up direction, pawl 843 will engage the seventh floor stopping collar 844 on tube 785. The tube 785 will now be moved in the up direction with the crosshead, operating bell crank lever 777 to open first, slow-down switch 135, and then stop switch 133. The car, and therefore the crosshead, will now be brought to a stop in a manner to be described later. It will be noted that the bell crank levers 777 and 790 are moved counter-clockwise about their pivots, during the switch opening operation, moving tube 785 and consequently stopping collar 844 to the left as well as upwardly. Thus, if there is excessive movement of the crosshead, due to the fact that the car has not been stopped, no injury to the selector machine will result because the stopping collar will finally be withdrawn from operative engagement with the pawl by the movement of the levers. The back surface 847 of each pawl is so inclined that, for example in the above operation, as the back surface of pawl 842 strikes a stopping collar, the pawl will slide over the collar without operative engagement. "Selector" switches 134 and 132 will be opened, due to the connection between tubes 785 and 797, at the same time as

switches 135 and 133 are opened. As the control circuits in which switches 134 and 132 are included are broken, due to the fact that the "director switch" is in up position, the opening of these switches is without effect 70 at this time.

"The selector" switches will be held in open position until the pawl magnet coil 114 is again energized. When this coil is energized, pawl 843 will be withdrawn from operative engagement with the seventh floor stopping collar. Weight 804 will then act to move tube 785 downwardly and tube 797 upwardly until stopped by the engagement of screw stop 801 and cross rod end piece 803. Bell crank levers 777 and 794 will thus be moved out of operative engagement with the abutment screws, permitting the "selector" switches to close.

Additional stopping collars, 847 and 848 on tube 785, and 849 and 850 on tube 797, may be provided for extra floor runs. Thus pawl 843 will engage stopping collar 848 to cause the opening of switches 135 and 133 to slow down and stop the car at the extra floor landing. As the car comes down from the extra floor landing, pawl 842 will engage stopping collar 850 causing the slow down and stop at the top floor. Similar operation is effected on an extra bottom floor run by collars 849 and 847.

Referring now to Figures 11, 14 and 18, a plurality of bars 852 of insulating material are arranged between standards 759 and 760 to form mountings for the selector machine 100 stationary contacts. Both of these standards are provided with a plurality of adjustable collars 853, the corresponding collars on each standard being arranged in horizontal alignment to form mountings for the bars 852. 105 The stationary contacts are arranged on the bars 852 in columns, designated as follows: 854, "down" hall stop contacts; 855, "up" and "down" car stop contacts; 856, "up" hall stop contacts; 857 and 858, "down" signal contacts; and 859 and 860, "up" signal contacts. Additional stationary contacts may be provided, also arranged in columns, designated as follows: 861, position indicator contacts; 448, "down" stop control contacts; 115 and 449, "up" stop control contacts. The stationary contacts are secured to the insulator bars 852, as by means of bolts 862. These bolts also secure insulating plates 863 on top of the stop contacts, for a purpose to be described later. The bars 852 for the intermediate floors are provided with contacts in each column. The tenth or top floor "down" hall stop, signal and stop control contacts may be omitted as no engagement is 120 made with them during normal operation. Similarly, the first or bottom floor "up" hall stop, signal and stop control contacts may be omitted. The other contacts shown in Figures 11 and 18 will be referred to during the 13

description of operation. The selector machine is provided also with moving contacts or brushes for engaging the various stationary contacts. The stop control, position indicator and signal brushes are mounted on a panel 864, secured, as by bolts 865, to bosses 866 on crosshead frame 822. Both the "up" and "down" signal brushes are arranged in four pairs in tandem, forming in effect four columns corresponding with the "up" and "down" columns of stationary signal contacts. Leading "down" signal brushes 317 and 318 are for completing the circuits for hall signals in advance of the car during down operation. The remaining "down" signal brushes 332, 333, 334, 335, 336 and 337 are for maintaining the circuit for the signals, brushes 336 and 337 acting when the car is at rest at the floor. The brushes of each pair of signal brushes, for example brushes 317 and 318, are electrically connected as by means of a plate 867. These plates are secured to the back of the panel 864 as by means of the brush mounting screws. Brushes 317, 332 and 334 are constructed in such a manner that they operate to complete a circuit only when the car, and therefore the cross-head, is moving in the down direction. The "up" signal brushes are arranged so as to function in the same manner during up travel of the car. Thus "up" brushes 868, 869 and 870, corresponding to "down" brushes 317, 332 and 334, will complete a circuit only when the car is traveling in the up direction. The construction of the brushes in this manner avoids the completion of undesirable circuits for the signal lamps of the various elevators of a bank. The position indicator brush 483 and stop control brushes 460 and 461, which may be provided, are similar in construction to brush 336 and will complete a circuit with the car operating in either direction.

The construction of the two types of brushes is shown in detail in Figures 21 to 25 inclusive. Referring to Figures 21, 22 and 23, the brush contact pieces 871 are pivotally mounted in the brush frame 872, as by means of a pin 873 supported by the frame arms 874. The brush contact pieces are preferably provided with slots 875, through which the pivot pin 873 extends, so as to permit their longitudinal as well as pivotal movement. Longitudinal recesses 876 are formed in the brush contact pieces to receive springs 877. These springs abut yieldingly against pivot pin 873, tending to maintain the contact pieces in their outer position. The frame arms 874 and washer 878 close slots 875 to maintain the springs 877 in position.

A centering blade 879 for the brush contact pieces is loosely mounted on guide bushing 880. The bushing 880, along with a washer 881, is secured to the yoke 882 of the brush frame 872 as by means of a screw 883. A compression spring 884 is mounted on bush-

ing 880 between centering blade 879 and washer 881. The outer end of the centering blade is bent in such manner as to form continuous engagement with the elongated surfaces of the contact pieces. Thus, when the brushes are not in engagement with a stationary contact, the centering blade will tend to maintain the brush contact pieces in central position. Upon engagement of the brush and a stationary contact, however, the contact pieces will be rocked about their pivot pin 873, moving the outer end of the centering blade to the left, as viewed in Figure 22, against the force of compression spring 884. It will be observed that the centering blade acts as a lever, slidably pivoted against yoke 882, further to compress the spring 884 during this operation. Thus, as the brush leaves the stationary contact, the compression spring causes the centering blade to restore the contact pieces to their central position. As the circuit completed by the brush and stationary contact is from the frame and centering blade into the contact pieces, it will be seen that the circuit is not broken by rocking the contact pieces in either direction about their pivot pin.

The construction of the brush shown in Figures 24 and 25, for example, "up" signal brush 868, is only slightly modified. In this construction the ends 885 of the frame arms 886 are joined to the main body 887 of the brush frame by means of strips 888 of insulating material. The brush centering blade 889 is bent differently, a portion of the outer end, adjacent to the brush contact pieces, supporting a strip 890 of insulating material. The brush contact pieces 871, when rocked into their counter-clockwise position, as viewed in Figure 25, by the engagement of the brush and a stationary contact during down car travel, will engage only the insulating strip 890, preventing the completion of a circuit. During up car travel however, the contact pieces will complete the circuit from the main body of the frame by way of the centering blade 889. In Figure 17 both forms of brushes are illustrated in various rocked positions which they may assume during up car travel.

Four brushes are employed to engage the stationary stop contacts, "up" hall stop brush 293 and "down" hall stop brush 270 for the contacts in columns 856 and 854 respectively, and "up" car stop brush 292 and "down" car stop brush 271 for the contacts in column 855. These brushes are of the type illustrated in Figures 21, 22 and 23, but are mounted in a different manner than the brushes above described. With the car at rest, the stop brushes assume a position relative to their stationary contacts such as illustrated in Figure 15. During the period of acceleration, however, the coil 207 of the brush magnet 891 is energized, causing the stop brushes 130

to advance to a position such as illustrated in Figure 16. The brush magnet frame 892 is carried by the crosshead frame 822, being secured thereto as by bolts 893. Frame 892 is arranged to receive the brush magnet 891. 5 Non-magnetic plates 894, positioned at each end of the brush magnet are secured to the frame 892 as by means of through bolts 895. These plates form a mounting for the brush magnet, being provided with recesses 896 into which the brush magnet core 897 extends. Pins 898, extending between the sides of the brush magnet frame, form pivotal supports for the brush magnet armatures 900 and 901. 10 A recess 902 is formed in each end of the core 897, through the non-magnetic plates to receive lugs 903 on the armatures 900 and 901. The non-magnetic plates further serve as spacing members to provide an air gap between the armatures 900 and 901 in their attracted position and the core 897, as illustrated in Figure 16. Thus retention of the armatures in this position by residual magnetism is prevented. 15 Armature 900 is extended beyond its pivot point to form an arm 904, the outer ends of the arm being provided with a slot 905. A brush arm 906, also pivotally mounted on pin 898, is secured to arm 904, as by means of 20 a set screw 907 extending through the slot 905. A lug 908 is formed on armature 900 to provide a mounting for a swivel 909. An eye bolt 910 is pivotally mounted, as by means of 25 a pin 911, on a similar lug 912 formed on the brush arm 906. The eye bolt 910 extends through the swivel 909, being secured thereto as by nuts 913, to form an adjustment between the armature and brush arm. The brush arm is provided with an adjustable 30 abutment screw 914 which engages the cross-head frame 822, with the brushes in normal or retarded position, i. e., the position which they assume with the car at rest or running at slow speed, to form a stop. The "up" stop 35 brushes 292 and 293 and a weight 915 are mounted on a panel 916. This panel is secured to the end of brush arm 906, the securing screws 917 extending through the weight 915. The weight acts as a bias tending to 40 turn the brushes 292 and 293 to their retarded position. The advanced position of the brushes may be altered by releasing the set screw 907 and adjusting the nuts 913 on eyebolt 910. After the correct advance position has been determined, the set screw 907 is again tightened. The retarded position of the brushes may be determined by means of 45 the adjustable abutment screw 914. 50 Armature 901 also is extended beyond its pivot point to form an arm 918. The slot 920 is formed in brush arm 921, the set screw 907 extending through this slot into armature arm 918. The "down" stop brushes 270 and 55 271 are similarly mounted on a panel 922 secured to the end of brush arm 921. The

weight 923, however, is formed on the end of the armature 901 adjacent to the brush magnet 891. The eye-bolt and swivel adjustment, abutment screw and armature lug are arranged in the same manner as described above. 70

In operation, as previously explained, the crosshead is raised and lowered by means of the screw 812 driven by the elevator car. The stop control, position indicator and signal brushes, the brush magnet and its brushes and the pawl magnet and its pawls, being carried by the crosshead, are therefore moved up and down in proportion to the movement of the elevator car. Assume that the car has 75 started from the first floor in the up direction. If there is no second floor call, the second floor stationary stop contacts in columns 855 and 856 will be "dead" so that the contact pieces for the "up" stop brushes 292 and 293 will 80 strike the insulating bar 852, rock and sweep across the stationary contacts without completing a circuit. As the car accelerates, the energization of the brush magnet coil 207 is 85 effected, causing the advance of the stop brushes. This brush advance may be effected before the second floor stop contacts are reached, depending on the distance between the floors. The manner in which the brush magnet coil is energized and the purpose of 90 the advance and retard of the stop brushes will be explained along with the description of operation of the system as a whole. Assume that the "up" third floor hall button has 95 been pushed. As will be seen from later description, hall stop contact 480 in column 856 will be "alive." Thus as the brush contact pieces of brush 293 sweep across contact 480, a circuit will be completed for causing the 100 initial slow down of the car and the deenergization of the pawl magnet. The position of the stopping collars 844 relative to the 105 position of the corresponding stationary stop contacts is such that, for example in the case assumed, pawl 843 will be released below the third floor collar. As the car continues its movement, the "selector" slow-down and stop 110 switches will be opened in the manner previously described, causing the final slow-down and stop of the car. At the same time the brush 115 293 will move past the contact and the brush magnet coil 207 will be deenergized. The weights 915 and 923 will act to move the stop brushes back into retarded position so that, 120 with the car stopped at the third floor, the relative positions of the parts will be as illustrated in Figure 15.

The stationary stop contacts are preferably short so that the slow-down distance may be made as nearly uniform as possible. 125 A long contact, such as illustrated for the signals, would permit response to the late operation of a car or hall button, i. e., the car might be caused to slow down when so near the floor that it would run past an un- 130

desirable distance. Similarly, the stop brush contact pieces are caused first to rock without making contact and then sweep across the contacts in order that a uniform slow-down distance as well as positive engagement may be assured. The insulating plates 863 on the top of the stop contacts cause the rocking of the brush contact pieces when the crosshead is being lowered.

A passage 925 for the "down" stop brushes is formed in the ninth floor insulating bar 852 to insure response to a ninth floor "down" call. Similarly, a passage 926 for the "up" stop brushes is formed in the second floor insulating plate 863 to insure response to a second floor "up" call. These passages are illustrated also in Figures 19 and 20. The manner in which these calls are responded to will be explained later.

Additional insulating bars 927 and 928 are provided for stop contacts 509 and 510 for the extra top floor and stop contacts 514 and 515 for the extra bottom floor respectively. The bars 927 and 928, contacts 509, 510, 514 and 515 and stopping collars 847, 848, 849 and 850, previously referred to, may be omitted in event that there are no extra floors. As it is generally desired to "make" such floors with one car only, these parts may be omitted from all the selector machines except one. On the other hand, more bars, stop contacts and stopping collars may be added if there are other extra floors, the "director switch" hatchway cams being arranged accordingly.

The leading signal brushes will operate to complete the circuit to the hall signals in advance of the car, the circuit being maintained by the brushes which follow. Thus with the "down" fourth floor signal contact 316 "alive," leading "down" signal brushes 317 and 318 will engage contacts 316 and 320 respectively to complete the signal lamp circuit. This circuit will be maintained by brushes 332-333, 334-335 and 336-337 engaging contacts 316 and 320 in sequence, brushes 336-337 being in engagement with these contacts with the car at rest at the fourth floor. The signal contacts are long as it is desired to provide continuous circuits. Further, the signal brushes are arranged so that each pair will not leave the contacts until after the engagement of the contacts by its succeeding pair, as may be seen upon reference to Figure 17 and to the diagram in Figure 33. The signal brush contact pieces are rocked by the signal contacts in the same manner that those for the stop brushes were rocked, the position of the signal brushes relative to their stationary contacts being such that the outer ends of the contact pieces will engage the contact with the car at rest at the floor. The "down" signal contacts 342 and 344 at the first floor are mounted on an insulating block 929 in order

to prevent their engagement by brushes 336 and 337 with the car at rest at the first floor. The circuit for the first floor signal lamp is maintained by the engagement of leading brushes 317 and 318 with additional signal contacts 345 and 346 mounted on insulating bar 930. The signal contacts for the top floor are similarly arranged.

Contacts 362 and 371, mounted on insulating bar 931, may be provided for a bottom floor annunciator switch. As these contacts are employed only for a reset operation, they are made short to correspond with the stop contacts. Similar contacts may be arranged for the top floor annunciator switch.

The position indicator brush 483 and contacts, column 861, are employed to complete circuits for the car position indicator lamps. Thus these contacts, as is the case with the signal contacts, are long in order that the indicator lamps may be lighted for most of the car travel. The brush 483 is positioned on the panel with its pivot point in line with the center of an indicator contact when the car is at rest at the floor. Thus the lighting of the indicator lamps for either direction of car travel is assured. The stop control brushes 460 and 461 are arranged to lead the stop brushes 293 and 270, even with the stop brushes in their advanced positions, as will be seen upon reference to Figure 34. It is apparent that the stop control brushes may be mounted on the panels 916 and 922, with their stationary contacts arranged accordingly. In such event stop control brush 460 will be given a slight lead over stop brush 293, and stop control brush 461 given a slight lead over stop brush 270, the stop control brushes being advanced by the brush magnet along with the stop brushes.

When the car is stopped at a terminal landing, for example floor ten, those brush contact pieces which are in engagement with contacts will be in a counter-clockwise rocked position, as viewed in Figure 17. When the car starts in the down direction, these brush contact pieces must reverse, that is, rock into a clockwise position. In the event that any of the brush contact pieces are caught in any manner, their reversal will be permitted by the slots 875 and springs 877. The distance between the various contacts is made to correspond to the distance between floors for the particular installation by adjusting the position of the insulating bar supporting collars 853 on the standards 759 and 760. The stopping collars 844 on tubes 785 and 797 are then adjusted to correspond. The leads (not shown) for the pawl magnet coil 114, brush magnet coil 207 and stop brushes 270, 271, 292 and 293 are connected in any suitable manner to certain of the binding posts 932 on panel 864. Others of the binding posts are provided for the brushes mounted on the panel. Flexible conductors (not shown) ex-

tend from these binding posts to similar binding posts (not shown) on panel 933. The flexible conductors are suspended in very much the same manner that flexible cables are suspended from an elevator car. 5 Panel 933 is secured to standards 757 and 758, as by means of clamps 934.

Reference may now be had to Figures 26 and 27 which illustrate the details of a preferred form of floor stop switch. Although 10 all the floor stop switches are identical in construction, the "down" fourth floor switch will be described in order to aid the description of operation of the system as a whole, 15 which follows. The switch frame 936 is mounted on the "stop and signal" panel 937, being secured thereto as by means of screws 938. The frame supports two cores, 939 for the upper or closing coil 296 and 940 for the 20 lower or reset coil 310. The middle portion 941 of the frame, extending outwardly between coils 296 and 310, forms a mounting on which a plate 942 is secured, as by screws 943. This plate extends over a portion of the 25 ends of both coils to retain them in position. A pin 944, supported by lugs 945 formed on plate 942, forms a pivotal mounting for the contact armature 946. The contact armature 946 extends upwardly to form an operating arm 947 for the movable contact 304. Contact 304 is slidably mounted in an aperture 948 formed in the end of arm 947, being insulated therefrom by means of insulating bushing 950 and washer 951. The bushing 30 and washer are mounted on the contact stem 952 with the flange 953, formed on bushing 950, abutting against the contact block 954. Nuts 955 serve to hold the contact parts in 35 assembled relation and to bind the terminal 40 clip for conductor 308 to the contact. The end of arm 947 is arranged between flange 953 and washer 951, being maintained against washer 951 with the switch in open position by means of a spring 956.

45 A support 957 for the stationary contact 304' is mounted on panel 937, being secured at the rear thereof as by a nut 958. The contact end of support 957 is threaded to receive the stem 960 of the holder 961 for contact 50 block 962. Thus the position of the stationary contact 304' relative to the position of the movable contact 304 may be adjusted, a nut 963 being provided on stem 960 for locking the stationary contact in adjusted position.

55 A pin 964, supported by additional lugs 965 formed on plate 942, forms a pivotal mounting for the latching member 966. This latching member, preferably of non-magnetic 60 material, comprises a pair of arms 967 and 968, through which pivot pin 964 extends, and a connecting yoke 969. The latching member is biased by weights 970, formed on arms 967 and 968, to turn counter-clockwise, 65 as viewed in Figure 27, the movement being

limited by the engagement of a lug 971, formed on the inner side of arm 967, and one of the mounting lugs 965. A projection 972, extending upwardly from yoke 969, cooperates with a lug 973, depending from the horizontally extending arm 974 of contact armature 946, to latch the contacts 304, 304' in closed position. 70

The armature 975 for the reset magnet is pivotally mounted on pin 964 between the 75 lugs 965. A lug 976 extends upwardly from the pivot point of the reset armature 975 to receive an adjustable abutment screw 977. A biasing weight 978, formed on the lower end of reset armature 975, tends to maintain the 80 armature in unattracted position with screw 977 abutting against the projection 980 formed on the extended portion 941 of frame 936. A lug 981, formed on the lower end of arm 967, extends in the path of the weight 85 978, to be struck thereby as the reset armature 975 is moved to its attracted position. Non-magnetic plates 982, provided on the outer 90 ends of cores 939 and 940, serve as spacing members to prevent the armatures 946 and 975 from being held in by residual magnetism. The terminals 983, provided on the coils 984, 296 and 310, and the binding nuts 984, provided on the end of contact support 957 extending to the rear of the panel, are for connecting the switch in the system, the connections to be described along with the description of the wiring diagram in Figure 33.

In operation, with the closing coil 296 energized in response to the pushing of its hall 100 button, contacts 304, 304' will be closed, spring 956 yielding to permit the engagement of contact armature 946 and non-magnetic plate 982. With contact armature 946 in this attracted position, the latching member 966 105 is free to move into position with projection 972 beneath the lug 973, such movement being caused by the action of gravity on the weights 970. Upon the deenergization of coil 296, contact armature 946 is moved outwardly by 110 the action of the spring 956 to cause the engagement of lug 973 and projection 972. As this movement is insufficient to cause the engagement of the end of arm 947 and washer 951, the contacts 304, 304' are latched in closed 115 position. The switch is illustrated in these figures in its latched position.

Upon the energization of reset coil 310, the reset armature 975 is moved to attracted position. The reset armature will gain in speed 120 as it is pulled in so that the weight 978 will strike the lug 981 a hammer blow. This blow insures the tripping out of the latch, i. e., the movement of projection 972 from under the lug 973, and therefore the release of the 125 contact armature 946. Armature 946 now falls under the action of gravity into the notch 983 formed in the projection 972, separating contacts 304, 304'. The outward movement of the contact armature is limited 130

by the engagement of lug 973 with a stop 987, forming one side of the notch 986.

Referring now to Figures 28 and 29, the preferred form of floor signal switch is identical in construction with the floor stop switch above described except that back contacts are provided. As in the case of the floor stop switch, the "down" fourth floor signal switch will be described. The arms 988 and 989 of the latching member 990 are extended below the reset armature biasing weight 978 where they are joined by a yoke 991. These arms 988 and 989 and yoke 991 are so formed as to permit the engagement of the lug 992 formed on arm 988 by weight 978, in the manner described above. The yoke 991 is formed with a depending lug 993 in which a movable contact 300, identical in construction with movable contact 304 of the floor stop switch, is slidably mounted. The contact support 994, or the stationary contact 300', is identical in construction with the contact support 957 for the floor stop switch, except that it is shortened. At the rear of the panel 937, the support is provided with the securing nut 958 and binding nuts 984. The large air gap between the reset magnet and armature, obtained by the preferred construction, prevents the premature tripping out of the latch when the switch, upon closing, completes the circuit for a signal lamp, the circuit for the lamp filament being through reset coil 331.

In operation, with the closing coil 301 energized, forward contacts 315, 315' will be closed, back contacts 300, 300' will be separated and projection 995 on latching member 990 will be moved under lug 973. Upon de-energization of closing coil 301, lug 973 will engage projection 995 to latch the forward contacts 315, 315' in closed position, as illustrated in the drawing. Upon energization of reset coil 331, weight 978 will not only trip out the latch for the forward contacts 315, 315' but also will cause the closure of back contacts 300, 300'. The lug 973 falling into the notch 996 will form a latch for the back contacts, retaining them in closed position. It will be noted that, upon the energization of the closing coil 301 again, the latch for back contacts 300, 300' is not released until the latching member 990 is free to move into position with projection 995 beneath lug 973, and therefore not until the forward contacts 315, 315' are closed.

The floor stop and signal switches for the intermediate floors are mounted in groups on the "stop and signal" panel 937, as illustrated in Figure 30. Each group comprises the "up" and "down" floor stop and signal switches for each floor. No stop or signal switches are provided for the first and tenth floors, these floors being made regular stops in a manner to be described later. However, floor annunciator switches, identical in construction with a floor signal switch, may

be employed to serve as part of a call system for these floors. The switches have been characterized generally in accordance with the floor and circuit in which they are included. For example, DS 2 indicates that the switch is in the "down" second floor stop circuit; UL 6 indicates that the switch is in the "up" sixth floor lamp or signal circuit; and UA 1 indicates that the switch is in the "up" first floor annunciator circuit.

A plurality of single pole, single throw knife switches are mounted on the panel 937 for cutting out of operation pairs of the switches in a group. Thus, for example, the opening of switch 302 will render the "down" fourth floor stop and signal switches unresponsive to the "down" fourth floor hall button. Similar knife switches are provided for the floor annunciator switches, for example, switch 360 for the "up" first floor annunciator switch.

Automatic non-stop switches 443, one for each elevator in the bank, also may be mounted on panel 937, two switches being shown by way of illustration. These switches are identical in construction with a floor stop switch except that two pairs of forward contacts are provided. Rotatable switches 997, one for each automatic non-stop switch, also may be mounted on the panel. Each switch has five positions, designated, *a*, *b*, *c*, *d* and *e*, indicating stop control, off, local, off and express positions respectively. The significance of these positions will be obvious from later description.

The control panel 998 for elevator No. 1 with its various switches is illustrated in Figure 31. No description will be given of this panel at this time as it is believed that it will be sufficiently understood from the description which follows.

Reference may now be had to Figures 32 and 33 which illustrate diagrammatically the various control and power circuits. No attempt is made in these figures to show the coils and contacts of the switches in their associated positions, "straight" diagrams being employed wherein the coils and contacts of the various switches are separated in such a manner as to render the circuits involved relatively simple. In order for a clearer understanding of the invention, the stationary contacts of the switches are illustrated in cross section. The relation of the coils and their contacts may be seen upon reference to Figure 31. It will be observed that Figure 32, taken in connection with the top portion and the left half, below the legend "Selector machine, elevator No. 1," of Figure 33, constitutes a complete wiring diagram for one elevator. The top portion and the right half, below the legend "Selector machine, elevator No. 2," of Figure 33 show the stop and signal control circuits for a second elevator, it being understood that the second

elevator is provided with a motor control system identical with that illustrated in Figure 32. As much of the diagram as relates to floors 5 to 9 inclusive has been omitted in Figure 33 since it is believed that the invention will be clear without the additional illustration and that the diagram will be much simpler.

Referring particularly to Figure 32, the numerals 1 to 5 inclusive indicate the mains of a multi-voltage source, as illustrative of one form of power supply suitable for the present system and adopted for convenience of representation. Transfer resistances 6 and 7, 8 and 9, and 10 and 11 are associated with the multi-voltage mains for purposes of acceleration and retardation. The main motor armature is designated by the reference character M while the auxiliary motor armature is designated by m. Separately excited shunt fields 12 and 13 are provided for the main motor and auxiliary motor respectively. The auxiliary motor may be provided also with a series field 14 to assist in the "pick up" under its fast speed operating conditions. Various electrodynamic brake resistances are employed, 15, 16, 17 and 18 for the main motor and 19 for the auxiliary motor. Field 12 is provided with a series resistance 20 and a discharge resistance 21. Similarly, field 13 is provided with series resistance 22 and discharge resistance 23. 24 is the main motor electromagnetic brake release coil while 25 is the auxiliary motor brake release coil. Coil 25 is provided with a permanent discharge resistance 26. The auxiliary motor is provided also with a starting resistance 27 for fast speed auxiliary operation and a slow-down resistance 28 for slow speed operation. The leveling switch is designated as a whole by the numeral 30, while the motor for moving the leveling switch out of the path of its cams is designated by numeral 31.

Various electromagnetic switches are provided which are designated as a whole as follows:

- A—Main potential switch,
- B—Main "up" direction switch,
- C—Main "down" direction switch,
- D—Main first accelerating switch,
- E—Main second accelerating switch,
- F—Main third accelerating switch,
- G—Auxiliary "up" direction switch,
- H—Auxiliary "down" direction switch,
- J—Auxiliary line switch,
- K—Auxiliary speed switch,
- L—Auxiliary accelerating switch,
- N—Brake resistance switch,
- O—Signal reset switch,
- P—"Down" non-interference switch,
- Q—"Up" non-interference switch,
- RA—Retardation control load switch,
- RB—Speed control load switch,
- RC—Brake control load switch,
- S—Door contact sequence relay,

- T—Auxiliary slow-down switch,
- U—Car stop switch,
- V—Hall stop switch,
- W—Valve motor switch,
- X—Automatic reset switch,
- Y—Fuse protective relay,
- Z—Sequence stop relay.

Throughout the description which follows, these letters, in addition to the usual reference numerals, will be applied to the parts of the above enumerated switches. For example, contacts B 35 will indicate that the contacts are on the main "up" direction switch, while operating coil A 41 will indicate that the coil operates the main potential switch. This will be made clear by reference to Figure 31.

Various safety switches, limit switches and door and gate contacts may be employed, reference to which may be had in connection with the description of the various circuits and of the operation of the system. It is assumed that the power main switch 32 a—e and the control line switch 33 a—b are closed.

According to the preferred arrangement, the main motor, when it is not in operation, is provided with a "standing field." This provision may be made by applying a reduced voltage to the field winding 12. The field circuit may be traced from power main 3, switch 32c, by way of line 34 through back contacts B 35 and C 36 of the direction switches and resistance 37, line 38, by way of line 39 through field 12, switch 32e to power main 5. It is not desired to apply the full voltage of mains 1 and 5 to the field because of increased power consumption. On the other hand, it is not desired to have the field deenergized when the motor is at rest as a matter of safety and because of the large time constant involved in building up. The "standing field" not only reduces the time constant, since the applied voltage is merely increased, but also prevents too sudden acceleration with heavy load on down motion or light load on up motion of the car.

The operating coil A 41 of the potential switch is energized from power main 1, switch 32a, fuse 29, line 1', by way of line 42 through switch 33a, coil A 41 and auxiliary back contacts A 43, car safety switch 44, by way of line 45 through "safety switches," indicated by legend, and contacts Y 46 of the fuse protective relay, line 5', fuse 29, switch 32e, to main 5. The back contacts A 47 and A 48 therefore are open and consequently the electrodynamic brake circuits, comprising the resistances 17 and 18 connected across the armature M, are broken. Also the forward contacts A 49 and A 50 are closed, preparing the motor armature circuit. Auxiliary forward contacts A 52 and A 53 are closed preparing the circuit for the brake release coil 24 and the circuit for the main accelerating switch coils respectively. Also, auxiliary back contacts

A 43 are separated inserting the cooling resistance 54 in series with the operating coil A 41.

Assume that the car is at some intermediate floor, for example, floor 4. The "director switch" 55 will be in one of its on positions as previously explained. For the convenience of description, the switch is shown in its down position. Thus the "down" non-interference switch coil P 56 is energized and consequently the back contacts P 57 and P 58 of this switch are open and the forward contacts P 60 and P 61 are closed. The function of contacts P 57, P 58 and P 61 will be evident from the description of operation of the system particularly relating to the selector machine. Contacts P 60 and the corresponding contacts Q 64 of the "up" non-interference switch form an electrical interlock 10 for the direction switch closing coils C 62 and B 63. Thus with contacts P 60 closed and contacts Q 64 open, completion of a circuit for coil C 62 will not establish a circuit for coil B 63 by way of coil P 56, coil Q 65 and line 66. The car button magnet coil 67, being arranged in series with coil P 56, also is energized. The circuit for coils P 56 and 67 may be traced from line 1', by way of line 68 through switch 33b, line 69, contacts 71 and 25 72, bridged by segment 70 of the "director switch," by way of line 73 through coil P 56, by way of line 74 through coil 67, safety switch 44, line 45, to main 5 as previously traced.

35 The condition of the system so far described is normal for the car at rest and the switches so far described are illustrated in their normal positions for down car travel. If the "director switch" is in "up" position, 40 it will close the circuit for non-interference coil Q 65 instead of coil P 56. The position of segment 70 may be different for the floors next to the top and bottom but this does not alter the above described circuits. The system 45 being in condition to start, upon the operator's moving the starting switch to position I, starting switch contacts 77 are bridged to complete a circuit for a suitable form of door and gate operating mechanism. For 50 convenience of illustration, contacts 77 are arranged to complete a circuit for valve motor switch operating coil W 78. The valve motor switch may comprise two switches interlocked in a manner similar to the direction switches, a single reference letter W however being used. This switch, upon operation, closes contacts W 79 and W 80 to complete a circuit for a "valve motor," indicated by legend. The valve motor operates a valve 55 for a gate engine (not shown), the engine operating in turn to close the gate. The circuit for coil W 78 may be traced from switch 33b, line 81, line 82, by way of line 83 through contacts 77 and coil W 78, line 5', fuse 29, 60 switch 32e, to main 5. The circuit for the

"valve motor" may be traced from line 81, by way of line 87 through a resistance 84 and valve motor series field 85, contacts W 79, the valve motor armature, contacts W 80, line 86, to line 5'. 70

If the operator, at any time after he has closed the gate and before he has advanced the starting switch to position II, desires to open the gate, or if he desires to arrest the movement while the gate is closing, he may 75 do so by moving the starting switch to position III. Contacts 88 will then be bridged to complete a circuit for coil W 89. As will be obvious from the description of the gate closing operation, the "valve motor" armature 80 circuit reverses through contacts W 90 and W 91. The "valve motor" will now operate the valve in such manner as to cause the engine to open the gate. Obviously other forms of power operated gate and door mechanisms 85 and arrangements for controlling such mechanisms may be employed without departing from the spirit of the present invention. The doors for each landing may be operated by the "valve motor" as is well understood in the 90 art. For example, each door may have a separate engine, the controlling valves therefore being operated by the engagement of a retiring cam, also operated by the "valve motor," and rollers provided on the ends of 95 the operating levers for the valves (not shown).

Referring now also to Figure 33, and particularly to the wiring diagram for selector machine, elevator No. 1, according to the 100 preferred arrangement, contacts 92 are bridged along with contacts 77 in position I of the starting switch as previously set forth. Closure of contacts 92 completes the circuits for coil U 93 of the car stop switch, 105 coil V 94 of the hall stop switch and the closing coil X 95 of the automatic reset switch. The various functions of these switches will be evident as the description proceeds. The circuit for coil U 93 may be traced from line 110 3', through line 96 and line 97, by way of line 98 through contacts 92, back contacts N 100 of the brake resistance relay, resistance 101, by way of line 102 through resistance 103, back contacts D 104 of the first accelerating 115 switch and coil U 93, line 105, to line 5'. The circuits for coils V 94 and X 95 may be traced from line 102, by way of line 106 through coil X 95, back contacts X 107 and coil V 94, line 105, to line 5' as before. 120

The car stop switch upon operation closes contacts U 110, U 112 and U 116, while the hall stop switch upon operation closes contacts V 111, V 113 and V 117. The current of the series circuit comprising coil V 94 and coil X 95, however, is not strong enough to cause the automatic reset switch X to act at this time. Contacts U 110 together with contacts V 111 form a by-pass for starting switch contacts 92, maintaining the circuits 125 130

for coils U 93, V 94 and X 95. Contacts U 112 and V 113 complete the circuit to the pawl magnet coil 114. Contacts U 116 and V 117 complete the circuit for the second and third accelerating switch coils E 126 and F 123, respectively.

The circuit for the pawl magnet coil 114 may be traced from line 3', line 96, line 97, by way of line 98 through contacts 92 and contacts N 100, by way of line 115 through contacts V 113, contacts U 112 and coil 114, line 105, to line 5'. With either contacts 92 or contacts N 100 open, the above circuit will be through the by-pass formed by contacts U 110 and V 111 and cooling resistance 101. This by-pass forms a holding circuit for the pawl magnet coil. The resistance 101 not only functions during normal operation but also serves to reduce power consumption and to eliminate overheating of coil 114 in case the operator has moved the starting switch to position I and then back to "neutral" without starting the car.

The circuit for the second and third accelerating switch coils may be traced from line 1', line 68, switch 33b, line 69, contacts 71 and 118, bridged by "director switch" segment 70, line 120, by way of line 121 through car slow speed switch 122, contacts U 116, contacts V 117, coil F 123, shunted by back contacts E 124 and resistance 125 in series, coil E 126, shunted by resistance 127, resistance 128, back contacts S 129 of the door contact sequence relay, back contacts RA 130 of the retardation control load switch and contacts A 53, a portion of transfer resistances 6 and 7, to line 2'. The voltage applied to the coils being of low value, there is no operation of the accelerating switches at this time.

The pawl magnet coil 114, however, retracts its pawls 842 and 843 allowing the "selector" stop switches 132 and 133 and "selector" slow-down switches 134 and 135 to close in the manner previously described. Due to the fact that the gate and doors have been closed, gate contacts 136 and a series of door contacts, indicated by a single set of contacts 137, are closed. The operator may now move the starting switch to position II to start the car.

With the starting switch in this position, contacts 138 are bridged to complete a circuit for coil S 140 of the door contact sequence relay, closing coil N 141 of the brake resistance switch and closing coil C 62 of the "down" direction switch, all arranged in series relation. At the same time contacts 138 complete a circuit for the oppositely wound coil S 142 of the door contact sequence relay. The circuit for the coils C 62, N 141 and S 140 may be traced from contact 72, by way of line 143 through contacts P 60, coil C 62, contacts 132, coil N 141, coil S 140, back contacts S 144, door contacts 137, gate contacts 136 and contacts 138, line

75, line 74, to line 5' as previously traced. The circuit for coil S 142 may be traced from line 69, by way of line 145 through coil S 142, contacts 138, line 75, line 74, to line 5'. 70

The purpose of the door contact sequence relay is to insure the closure of the gate and doors before starting the motor. When coils S 140 and S 142 are energized simultaneously, the coils being differentially wound, the door contact sequence relay is not operated. If either coil S 140 or coil S 142 is energized ahead of the other, or if either coil alone is energized, contacts S 144 will open preventing the starting of the car. If, when contacts 138 are closed, any of the contacts P 60, 132, 137, or 136 are open, coil S 142 alone will be energized resulting in the opening of contacts S 144. One of the reasons why it is preferred to bridge contacts 92 85 ahead of contacts 138 is to insure the prior closure of the "selector" stop switches 132 and 133 and slow-down switches 134 and 135. Similarly, contacts 77 are bridged ahead of contacts 138 to effect the prior closure of the gate and door contacts. It will be obvious, therefore, that the car cannot be started on the gate contacts. The door contact sequence relay is provided with additional contacts S 129. These contacts 95 will be separated to stop the motor if the gate or door is opened while the car is running. After the first accelerating switch D has operated, the "down" direction switch will be maintained in operated position by holding coil C 146, unaffected by contacts S 144. When contacts S 129 separate, however, operating coil D 170 of the first accelerating switch will be deenergized. The circuit for coil C 62 being open at contacts S 144, the direction switch will drop out due to the fact that the circuit for its holding coil is open at contacts D 197. 105

Upon operation of the "down" direction switch in response to the energization of its closing coil C 62, contacts C 147 and C 148 separate, breaking the electro-dynamic brake circuits comprising the resistances 15 and 16, and the contacts C 149 and C 150 close, completing the circuit for the motor armature M. 115 The circuit for the motor armature may be traced from line 1', by way of line 151 through contacts A 49, by way of line 152 through contacts C 149, by way of line 153 through the reactance coil 154 and the motor armature M, by way of line 155 through contacts C 150, contacts A 50, and current coils RA 156 and RC 157 of the load switches, through contacts D 190, to line 2'. Also contacts C 36 separate so that, with contacts C 149 120 closed, the field 12 is connected across mains 1 and 5. The circuit for the field may now be traced from line 152, by way of line 158 through back contacts B 160 of the "up" direction switch and a portion of resistance 16, 125 contacts C 149 and C 150, to line 2'. The circuit for the motor armature may be traced from line 155 through contacts C 150, contacts A 50, and current coils RA 156 and RC 157 of the load switches, through contacts D 190, to line 2'. Also contacts C 36 separate so that, with contacts C 149 130 closed, the field 12 is connected across mains 1 and 5. The circuit for the field may now be traced from line 152, by way of line 158 through back contacts B 160 of the "up" direction switch and a portion of resistance 16, contacts C 149 and C 150, to line 2'.

- line 161, by way of line 34 through back contacts F 162, line 38, by way of line 39 through field 12, to line 5', as previously traced. The direction switch is provided also with contacts C 163 which close to complete a circuit for the brake release coil 24. This circuit may be traced from line 158 and a portion of resistance 16, by way of line 161 through coil 24, contacts RC 164, contacts A 52, coil O 165 of the signal reset switch and contacts 166, by way of line 167 through contacts C 163, to line 5'. Energization of the brake coil releases the brake, permitting the motor to start. The direction switch is provided further with auxiliary forward contacts C 168 and auxiliary back contacts C 169, the purpose of contacts C 168 being to complete the circuit for the first accelerating switch coil D 170, and the purpose of contacts C 169 being to prevent energization of the holding coil B 177 for the "up" direction switch when auxiliary contacts D 178 close in response to the energization of coil D 170. The circuit for coil D 170 may be traced from segment 70 and contact 172, by way of line 173 through contacts 134 and contacts C 168, by way of line 174 through coil D 170, shunted by resistance 175, and contacts D 176, line 121, to line 2' as previously traced.
- 30 The brake resistance switch N operates substantially simultaneously with the direction switch C. Thus contacts N 100 separate to break the circuit through line 98 so that if the operator, after starting the car, should 35 return and hold the starting switch in position I, bridging contacts 92, the pawl magnet coil will not be overheated. Contacts N 180 close to by-pass starting switch contacts 138. The starting switch may now be released 40 whereupon it will be automatically centered in "neutral" position. Contacts N 181 close to prepare another circuit for the automatic reset switch closing coil X 95, the purpose of which will be set forth in later description.
- 45 Additional contacts N 182 may be provided on this switch to close the circuit to suitable mechanism, such as a motor 31, for withdrawing the leveling switch 30 from the path of its cams. This circuit may be traced from 50 line 1', line 68, switch 33b, line 81, line 87, by way of line 183 through contacts N 182, resistance 184, motor field 185 and armature 186, line 187, line 75, line 74, to line 5' as previously traced.
- 55 The energization of the first accelerating switch operating coil D 170 will cause the closure of power contacts D 189 and D 191 and auxiliary contacts D 197 and D 178 and the separation of power contacts D 190 and D 192 60 and auxiliary contacts D 176 and D 104. Of the power contacts, first contacts D 189 close to connect the transfer resistance 6 across lines 2' and 3', the circuit being from line 2', through contacts D 192, contacts D 190, line 65 193, resistance 6, contacts D 189, line 194, con-
- tacts E 202, contacts E 204, to line 3', and contacts D 190 separate to place resistance 7 in series with resistance 6 across lines 2' and 3'. Then contacts D 191 close and contacts D 192 separate to connect the motor armature directly to line 3' and break the connection to line 2' respectively. Of the auxiliary contacts, contacts D 176 separate to insert cooling resistance 195 in series with the operating coil D 170. Contacts D 104 separate to insert cooling resistance 196 in series with coil U 93. Contacts D 197 close to complete a circuit for holding coil C 146 of the "down" direction switch and holding coil N 198 of the brake resistance switch. Contacts D 178 close in the circuit for the holding coil B 177 of the "up" direction switch but this closure has no effect during the period of down travel since the circuit for coil B 177 is open at contacts C 169, as previously set forth. The circuit for coils C 146 and N 198 may be traced from line 68, by way of line 69 through coil C 146, back contacts B 199 and contacts D 197, by way of line 200 through coil N 198, to line 5'.
 70 75 80 85 90 95 100 105 110 115 120 125 130
- It is preferred to provide the accelerating switches with mechanical interlocks to insure proper sequence of operation. A form of interlock which has been found suitable, illustrated in Figures 36 and 37, will be described later. It is to be noted that, with the transfer of the motor armature circuit to line 3', a higher voltage is applied to the coils E 126 and F 123, due to the fact that line 121 also is transferred to line 3'. Sufficient current is now supplied to coil E 126 to cause the operation of the second accelerating switch. A copper sleeve (not shown) may be provided to give the switch a time element, as is well understood by those versed in the art.
 95
- The switch E operates to transfer the motor armature M from line 3' to line 4', the operation of the power contacts E 201, E 202, E 203 and E 204 and resistances 8 and 9 being the same as the operation of the power contacts of switch D and resistances 6 and 7. The switch is provided also with auxiliary contacts E 206, E 124 and E 210. Contacts E 206 close to complete a circuit for brush magnet coil 207 and voltage coil RB 208 of the speed control load switch. This circuit may be traced from line 121, by way of line 209 through coils 207 and RB 208 in parallel and contacts E 206, back to line 121 and thence to line 3' as previously traced. Contacts E 124 separate to break the shunt circuit, comprising resistance 125, for coil F 123. Contacts E 210 close to short circuit resistance 128 in series with coil F 123. These last two operations, in conjunction with the fact that line 121 has been transferred to a still higher voltage line, permit sufficient current to be taken by coil F 123 to effect the operation of the last accelerating switch.
 120 125 130

The switch F now operates to transfer the motor armature to line 5', the operation of contacts F 211, F 212, F 213 and F 214, along with resistances 10 and 11, being the same as that of the power contacts and transfer resistances of the first and second accelerating switches. The motor armature circuit may now be traced from line 1', by way of line 151 through contacts A 49, by way of line 152 through contacts C 149, by way of line 153 through reactance coil 154 and the motor armature M, by way of line 155 through contacts C 150 and A 50, by way of line 215 through contacts F 213 and current coil RB 216 of the speed control load switch, to line 5'. The purpose of the reactance coil 154 is to smooth out the voltage steps as will be readily understood by those skilled in the art.

It will be noted that the current coil RB 216 of the speed control load switch is now energized. The switch is so adjusted that its voltage coil RB 208 alone will not operate it. However, when the motor armature is taking current from the line, the coils RB 208 and RB 216 assist each other to operate the switch, separating contacts RB 217. Auxiliary back contacts F 162 are separated upon operation of switch F. Separation of contacts RB 217 and contacts F 162 inserts all of resistance 20 in the shunt field circuit to bring the motor up to full speed. If at any time the motor operates under negative load conditions, i. e., light load up or heavy load down for an over counterweighted elevator, the current coil RB 216 will oppose the voltage coil RB 208, permitting the closure of contacts RB 217. Closure of these contacts short circuits a portion of resistance 20 to strengthen the field, slowing down the motor.

It will be understood that had the "director switch" segment 70 been in up position bridging contacts 291, 702, 703 and 508, "up" direction and non-interference switches B and Q, instead of "down" direction and non-interference switches C and P, respectively, would have been operated. The "up" direction switch has power contacts B 218, B 160, B 219 and B 220, corresponding to and operating in place of "down" direction switch power contacts C 147, C 148, C 149 and C 150 respectively, and has auxiliary contacts B 35, B 221, B 222 and B 199, corresponding to and operating in place of auxiliary contacts C 36, C 163, C 168 and C 169. The "up" non-interference switch has contacts Q 283, Q 325, Q 64 and Q 294, corresponding to and operating in place of "down" non-interference switch contacts P 57, P 58, P 60 and P 61.

The motor and car will continue to run at full speed until stopped by one of the many stopping arrangements. Stopping by means of the "director switch" hatchway cams will now be described. It is assumed that the

car has started from floor 4 and that it has gotten up to full speed. As the car nears the bottom floor, the roller 738 on the "director switch" operating arm 737 strikes the hatchway cam, moving the bridging segment 70 off contact 118. The circuit for coils E 126 and F 123 is thus interrupted. The switch F, having no time constant, drops out immediately, resulting in the connection of the motor armature to the next lower voltage step. The power contacts of switch F operate in inverse order so that the transfer from line 5' to line 4' is gradual. The circuit through current coil RB 216 is broken upon separation of contacts F 211. Contacts RB 217 and contacts F 162 close to short-circuit resistance 20 strengthening field 12 for regenerative braking during the slow down operation. Switch E also drops out, retarded however by the copper sleeve and discharge resistance 127 as will be readily understood. The motor armature is now transferred from line 4' to line 3'. Auxiliary contacts E 124, E 206 and E 210 return to their original positions in preparation for the next starting operation.

As the roller rides farther down on the cam, the "director switch" segment 70 moves off contact 172, breaking the circuit for coil D 170. Switch D now drops out, retarded however by its discharge resistance 175, transferring the motor armature from line 3' to line 2'. It will be understood that the mechanical interlocks function during the period of retardation to insure the operation of the accelerating switches in inverse sequence. Auxiliary contacts D 197 separate, breaking the circuit for holding coils C 146 and N 198. Contacts D 178 separate and contacts D 176 and D 104 close in preparation for the next starting operation.

As the car approaches still closer to the bottom landing, the hatchway cam will move the "director switch" to neutral and then reverse position. As a result, the segment 70 moves off contact 71 and then contact 72, de-energizing coils P 56, C 62 and N 141.

"Down" non-interference switch P drops out, separating contacts P60 and P61 and closing contacts P57 and P58. Separation of contacts P60 prevents the establishment of a circuit for coil C62 upon the completion of a circuit for coil B63 as will be obvious from previous description. The purpose of the separation of contacts P61 and the closure of contacts P57 and P58 will be obvious from later description. "Down" direction switch C drops out, separating power contacts C 149 and C 150 and auxiliary contacts C 163 and C 168 and closing power contacts C 147 and C 148 and auxiliary contacts C 36 and C 169. Contacts C 149 and C 150 disconnect the motor armature from the power mains while contacts C 147 and C 148 connect electrodynamic brake resistances 15 and 16 respectively.

tively, across armature *M*. It is preferred to arrange contacts C 147 and C 148 to close in sequence as indicated in Figure 31. Separation of contacts C 163 deenergizes the brake release coil 24. The brake shoes will be applied, which, along with the action of the electro-dynamic brake resistances, will bring the motor to a stop. The closure of contacts C 36 will reconnect the field to lines 3' and 5', as will be obvious from previous description. Contacts C 168 and contacts C 169 are prepared for the next starting operation.

The switch N drops out along with the direction switch, separating contacts N 182, N 181 and N 150 and closing contacts N 224 and N 100. The separation of contacts N 182 deenergizes the leveling switch motor 31. The separation of contacts N 181 and N 180 is in preparation for the next starting operation, contacts N 180 breaking the by-pass circuit around starting contacts 138. Contacts N 224, being on the smaller and faster switch, close substantially at the same time that contacts C 163 separate, connecting discharge resistance 225 around coil 24 to "soften" the brake. The closure of contacts N 100 is in preparation for the next starting operation.

The leveling switch motor being deenergized, the leveling switch is moved into position for its operating rollers to engage the leveling cams. For convenience of description it is assumed that the main motor is stopping with the car still above the floor. Leveling switch contacts 226, 226' and 227, 227' close completing the circuits for coils J 228 and H 230 and coil K 231 respectively. The circuit for coils J 228 and H 230 may be traced from line 81, coil J 228, by way of line 232 through back contacts G 233 of the auxiliary "up" direction switch and coil H 230, contacts 226, 226', line 187, to line 5' as previously traced. The circuit for coil K 231 may be traced from line 81, line 82, by way of line 234 through coil K 231, line 235, contacts 227, 227', line 236, contacts 226, 226', line 187, to line 5'. It is to be noted, due to the fact that the circuit for coil K 231 is through contacts 226, 226', that the circuit for coil H 230 must be made in order for the circuit for coil K 231 to be completed. The auxiliary line switch J now operates to close contacts J 237, preparing the circuit for the auxiliary motor, and to close auxiliary contacts J 238, preparing a control circuit hereinafter described. Auxiliary "down" direction switch H also operates, separating contacts H 239 and H 240 and closing contacts H 241 and H 242. Separation of contacts H 239 disconnects electro-dynamic brake resistance 19 from across the auxiliary motor armature *m*. The auxiliary speed switch K also operates, separating contacts K 243 and closing contacts K 244. Closure of contacts H 241, H 242 and K 244 completes the auxiliary motor circuit for fast

speed operation. The circuit for armature *m* may be traced from line 1', contacts J 237, by way of line 245 through contacts H 241 and back contacts G 246, armature *m*, by way of line 247 through contacts H 242, line 248, contacts K 244, resistance 27, series field 14, to line 5'. The circuit for shunt field 13 may be traced from contacts J 237, by way of line 250 through resistance 22 and field 13, to line 5'. The circuit for brake release coil 25 may be traced from contacts H 241, by way of line 251 through coil 25 to line 250. The switch K also separates auxiliary back contacts K 252. As back contacts K 252 separate before forward contacts J 238 close, closure of the latter contacts has no effect at this time other than to prepare the control circuit as above stated.

The auxiliary motor armature and field circuits being complete and the brake released, the auxiliary motor starts, driving the elevator through the main motor brake. The main motor brake rotates, serving as a clutch for the auxiliary motor, a form of drive which is well understood in the art. The auxiliary motor will assume the drive of the elevator as the main motor is stopping, giving smooth operation. The auxiliary motor accelerates subject to the operation of short circuiting accelerating resistance 27 and series field 14. This operation is effected in the usual manner, the resistance and field being short-circuited in steps by means of contacts L 253, L 254, L 255 and L 256 subject to the control of C. E. M. F. coil L 257. Auxiliary contacts L 258 close along with contacts L 253 to insert a resistance 259 in parallel with coil H 230. Thus, so long as contacts L 258 are closed, coil H 230 will receive sufficient current to hold in but not enough current to operate. Resistance 259, therefore, not only serves to cool the operating coils H 230 and G 260 of the auxiliary direction switches but also forms an electrical interlock between them. Back contacts G 233 and H 240 form an additional interlock in the manner well understood in the art.

As the car nears the exact floor level, due to the contour of the leveling cams and the construction of the leveling switch itself, as will be described in connection with Figure 38, contacts 227, 227' separate, deenergizing coil K 231. Switch K drops out, separating contacts K 244 and closing both contacts K 243 and auxiliary contacts K 252. The auxiliary motor armature *m* is thus disconnected from line 5' and connected to line 3', the connection being through slow-down resistance 28. This resistance is provided to "cushion" the motor at the instant of change. Closure of contacts K 252 completes a circuit for coil T 263 of the auxiliary slow-down switch. Operation of this switch separates contacts T 264, breaking the circuit for C. E.

M. F. coil L 257, and closes both contacts T 265 and contacts T 266, short-circuiting slow-down resistance 28 and shunt field resistance 22 respectively. The auxiliary motor now brings the car at a slow speed to an exact level with the floor, leveling switch contacts 226, 226' separating to deenergize coils J 228 and H 230. The switches J and H drop out, disconnecting the motor which is brought to a full stop due to the re-insertion of electrodynamic brake resistance 19 at contacts H 239, the resistance functioning on a dying field, and the application of the brake shoes, the brake release coil 25 being deenergized upon separation of contacts H 241. If the car overruns the floor, the leveling operation will be the same except that the auxiliary motor switches for up direction of travel will be closed. The auxiliary "up" direction switch contacts are designated G 267 and G 268. It is believed that such operation will be obvious from the description of operation above set forth.

It is preferred to have the gate and door open automatically upon each floor stop. This may be done by providing line 269 to shunt contacts 88 when both contacts J 238 and K 252 are closed. With such an arrangement, the gate and door will open while the car is in the slow speed leveling zone so that completion of the door opening operation and the leveling of the car occur substantially at the same time. It will be noted that contacts J 238 separate when switch J drops out in the final leveling operation so that further automatic operation of the door and gate operating mechanism is prevented. Thus, when the operator moves the starting switch to position I causing the closing of the door and gate, the door and gate will remain closed. Obviously, other connections or circuits may be employed to effect the automatic door opening operation.

Although the "director switch" may act to stop the car in the above described manner, its major purpose is to determine the direction of travel of the car. It is preferred to employ the selector machine primarily to effect all normal stopping operations, permitting the "director switch" to insure the stop at the terminal floors. Referring now more particularly to Figure 33 and the circuits associated with selector machine, elevator No. 1, the stopping operation at the bottom floor as effected by the selector machine will now be described.

Assume that the car has started down from floor 4 and has attained full speed as previously described. Contacts E 206 are therefore closed and the brush magnet coil 207 is energized, advancing the stop brushes. Provision for advancing the brushes is made in order to meet the local running conditions; that is, when the car is running at full speed it requires a longer slow-down period than when

running from floor to floor. "Down" stop brushes 270 and 271, being advanced, will engage the bottom floor stop contacts 272 and 273 when the car is about fifteen feet from the floor, such a distance having been found a satisfactory one in practice within which to perform the slow-down and stop operations for a car running at 800 feet per minute. It will be observed that no car or hall buttons are provided for the top and bottom floors, contacts 272 and 273 being connected directly to a power line. Keeping these contacts permanently "alive" in this manner assures a stop on the selector machine at these limit floors. Engagement of car stop brush 271 and contact 273 establishes a short circuit for coil U 93 of the car stop switch while engagement of hall stop brush 270 and contact 272 establishes an additional circuit for coil X 95 of the automatic reset switch. The short circuit for coil U 93 may be traced from line 274 at resistance 196, through contacts Z 275 which are closed as the motor starts to prepare circuits for the car stop brushes as will be explained later, line 276, contacts P 61, brush 271, contact 273, line 277, to line 105. The additional circuit for coil X 95 may be traced from line 96, line 97, by way of line 102 through contacts V 111 and U 110, line 106, coil X 95, contacts X 107, line 278, by way of line 280 through non-stop switch 281, automatic non-stop switch contacts 444, contacts N 181, by way of line 282 through back contacts Q 283, brush 270, contact 272, line 277, line 105, to line 5'. As this latter circuit, bypassing coil V 94, permits increased current flow to coil X 95, the automatic reset switch operates to separate contacts X 107, deenergizing coil V 94. Coil U 93 being short circuited, the car stop switch drops out, separating contacts U 110, U 116 and U 112 and, coil V 94 being open circuited, the hall stop switch drops out, separating contacts V 111, V 117 and V 113. The separation of contacts U 110 and V 111 is in preparation for the next starting operation. The separation of contacts U 116 and V 117 deenergizes the coils of the second and third accelerating switches E and F. These switches now function in the stopping operation to retard the main motor in the manner previously described. The separation of contacts U 112 and V 113 deenergizes the pawl magnet coil 114 to release the pawls. As the selector machine crosshead continues its movement, the "down" pawl 842 engages the first floor stopping collar 844, causing the contacts 134 and contacts 132 to separate in sequence as has previously been described in connection with Figure 13. Separation of contacts 134 deenergizes the coil of the first accelerating switch D, further retarding the motor. Separation of contacts 132 breaks the circuit for the direction switch closing coil C 62 and the brake resistance switch closing coil N 141, stopping the main motor and

causing the auxiliary motor to bring the car to a level with the floor in the manner previously described. It will be observed that the separation of either contacts U 116 and 5 U 112 or V 117 and V 113 will effect the slow-down and stop operations above described.

The purpose of the retardation control load switch RA and the brake control load switch RC is to aid in stopping the car level with a 10 floor under varying conditions of load and speed. These switches are provided with voltage coils RA 261 and RC 262 connected in such a manner that their applied voltage is always that of the line less the voltage 15 across the motor armature M. Thus, at the instant of starting the motor, the voltage applied to these coils will be a maximum and, when the motor is running at full speed, the voltage applied will be substantially zero. 20 The circuit for the voltage coils is completed by direction switch auxiliary contacts C 163 and may be traced from line 1', by way of line 151 through contacts A 49, by way of line 152, through contacts C 149, line 153, through 25 reactance coil 154 and armature M, by way of line 155, back contacts B 218, a portion of resistance 15, by way of line 167 through coils RA 261 and RC 262, arranged in parallel, and contacts C 163, to line 5'. The 30 switches are preferably adjusted so that their voltage coils alone will not operate them. As has been indicated in tracing the power circuits for the motor armature, these switches are provided also with current coils RA 156 and 35 RC 157. The switches will not operate when the motor armature is taking current from the line as the voltage coil and current coil of each switch are arranged to act in opposition under these conditions. When, 40 however, the motor changes to a generator and returns current to the line, as it may do during the retardation period, the coils, acting cumulatively, may cause the switches to operate. The switches may be adjusted to 45 operate at any desired value of total ampere turns, such adjustment being determined by the particular installation. It is to be noted that the effectiveness of the voltage coils increases as the accelerating switches drop out. 50 Thus the load switch RC, for example, may not operate until after the motor armature circuit has been transferred back to main 2.

The load switches are inactive during the period of full speed operation of the motor 55 due to the fact that their current coils are shunted by a circuit comprising line 215 and contacts F 213. As the deenergization of switch coil F 123 is normally caused by the separation of contacts U 116 or V 117 and as 60 the separation of these contacts is caused by the engagement of a selector machine brush and "live contact", it may be said that the switches are rendered active in response to the operation of the selector machine. The 65 switches are preferably adjusted so that the

slow-down and stop operation is governed entirely by the selector machine when the motor is "lifting" a load. When, however, the motor is "lowering" a load, that is, a light load up or a heavy load down, the load 70 switches act automatically. The switch RA, therefore, may operate in advance of the "selector" slow-down switch 134 to deenergize the first accelerating switch coil D 170 by separating contacts RA 130. Thus the re- 75 generative braking effect is increased with the car at a greater distance from the landing, causing the motor to be running at a slower speed when the final stopping opera- 80 tion is initiated. Similarly, the switch RC 85 may act in advance of the "selector" stop switch 132 to insert a resistance 223 in series with brake release coil 24, with the result that the brake shoes are partially applied, causing the motor to be running at a still 85 slower speed when the final stopping opera- 90 tion is initiated.

Under normal operating conditions, the stops at the intermediate floors are made in response to the pushing of car or hall buttons. The stop operation in response to the pushing of a car button will now be de- 95 scribed.

Assume that a "down" traveling car has taken on passengers at the sixth floor and 95 that these passengers have called the third and second floors. The operator now pushes car buttons 653 and 652 and moves the starting switch to position I, closing the gate and door, and then to position II, starting the 100 car. Or, the operator may start the car and push the car buttons while the car is running. As has been previously explained, these buttons once pushed will be held in closed position by the car button magnet coil 105 67. Thus a circuit is prepared to third floor car stop contact 285 and second floor car stop contact 286, rendering them "alive". Upon the engagement of brush 271 and contact 285 a short circuit is again established for the 110 car stop switch coil U 93. This circuit may be traced from line 274 at resistance 196, contacts Z 275, line 276, contacts P 61, brush 271, contact 285, line 287, push button 653, to line 105. Coil U 93 being short-circuited, 115 the car stop switch will drop out, separating contacts U 116 and U 112. Separation of contacts U 116 effects the initial slow-down while separation of contacts U 112 effects the further slow-down and stop of the car in the 120 manner previously described. Incidentally, separation of contacts U 110 deenergizes coils V 94 and X 95 but without effect at this time as no hall buttons have been pushed.

On a run of several floors, such as has just 125 been completed, the slow-down is effected with advanced brushes. During the slow-down however, contacts E 206 are separated, deenergizing the brush magnet coil 207, whereupon the brushes are brought back to 130

their retarded position. Such retardation is to be desired since a permanent advance of the brushes might carry them beyond the next floor contacts. For example, upon a stop at the third floor such as just described, with the distance to the second floor only twelve feet, brush 271, advanced, might be below contact 286. Thus the car, upon being started again, would not stop at the second floor in response to the second floor car button.

The brushes being in retarded position however, the car, upon being started again, will stop in response to the car button at the second floor. Depending upon the distance between floors, brush 271 may engage contact 286 before switch E operates to complete the circuit for the brush magnet coil 207. Once this engagement is made, due to the shunting of coil U 93 and consequent separation of contacts U 116, switches E and F cannot operate. Therefore, the brush magnet coil will not be energized and the motor cannot accelerate to full speed. Thus the shorter slow-down range, due to the comparatively late engagement of the brush and contact, will be sufficient. Even though the brush magnet coil does become energized during this floor to floor run, if brush 271 in its downward movement sweeps across contact 286, the slow-down operation will immediately become effective. With the exception of the initiation of the slow-down operation, the stop at the second floor is made in the same manner as the stop at the third floor, above described.

In some installations the distance between certain floors may be so short that, for example, with the car at rest at the third floor, brush 271 may be touching contact 286. The short circuit, which would be established for coil U 93 with contact 286 "alive", is not complete however because the circuit to the brush is not prepared until contacts Z 275 of the sequence stop relay are closed. Since the operating coil Z 288 of the relay is connected in parallel with the brake release coil 24, contacts Z 275 are not closed until contacts C 163 are closed and therefore not until the starting switch is moved to position II. Thus, when the starting switch is moved to position I, the energization of the pawl magnet coil 114 is effected in the previously described manner so that, when the starting switch is moved on to position II, contacts 132, 133, 134 and 135 will be closed and the motor will start.

The stop at the second floor having been completed, the car, upon being started by the operator, will proceed to the bottom floor where it will stop in the manner previously described. The car may not get up to full speed as will be evident from the description of the run from the third to the second floor. Furthermore, in event of another

"short" floor, the "director switch" segment 70 may be moved off contact 118 by the engagement of its cam and roller at the second floor, preventing the operation of the second and third accelerating switches and the advance of the brushes. As the bottom floor stop is made, the "director switch" will be moved to its up position as previously described. As a result, it will be observed that the car button magnet coil 67 will be deenergized as segment 70 moves off contact 71. All the car buttons which have been pushed are thus released or reset to their original open circuit position. Coil 67 will be reenergized when its circuit is completed by the engagement of segment 70 and contact 291.

It is to be noted from the above description that response will always be had to car buttons, regardless of the order in which they are pushed, since a button, once pushed, is held down by the car button magnet, maintaining the car stop circuit prepared until the "director switch" is moved to "neutral" position. Similarly, response will be had regardless of the time during the run that a car button was pushed, so long as the "down" car stop brush 271 with the car traveling in the down direction, or "up" car stop brush 292 with the car traveling in the up direction, has not passed the corresponding car stop contact for that floor. Thus on a down run for example, the car will respond to the sixth floor car button pushed at the eighth floor, the fourth floor car button pushed at the fifth floor, the third floor car button pushed at the seventh floor and the second floor car button pushed at the tenth floor. It will be observed that no signal is lighted due to car button operation.

It will be observed that none of the "down" hall buttons were pushed and therefore none of the "down" hall contacts were "alive" in the above described operations so that no circuit was completed by hall stop brush 270. Also the circuits including the "up" car stop brush 292 and the "up" hall stop brush 293 were open at contacts Q 294 and contacts P 57 respectively. Thus, even though an "up" hall button has been pushed, there would be no response during down operation.

A stopping operation in response to the pushing of a hall button will now be described. Assume that the car is at rest at the sixth floor and that a prospective passenger at the fourth floor pushes "down" hall button 295, completing a circuit for closing coil 296 of the "down" fourth floor stop switch. This circuit may be traced from power main 4, line 298, by way of line 299, through back contacts 300, 300' of the "down" fourth floor signal switch, coil 296, closing coil 301 of the floor signal switch, cut-out switch 302 and push button 295, line 303, to power main 5. The floor stop switch will operate in the manner previously described

in connection with Figures 26 and 27 to latch contacts 304, 304' in closed position. It will be observed that, along with the operation of the floor stop switch to close contacts 304, 304', the floor signal switch operates to separate back contacts 300, 300'. Thus, until contacts 300, 300' are again closed, if the prospective passenger should again push hall button 295, no circuit would be completed. The utility of these back contacts will be more evident from further description. Closure of contacts 304, 304' prepares a circuit for "down" fourth floor hall stop contact 305, rendering it "alive."

Assume now that the car has started down. As it nears the fourth floor, hall stop brush 270 will engage contact 305, establishing an additional circuit for closing coil X 95 of the automatic reset switch. This circuit may be traced from line 96, line 97, by way of line 102 through contacts V 111 and U 110, line 106, coil X 95, contacts X 107, line 278, by way of line 280 through non-stop switch 281, automatic non-stop switch contacts 444 and contacts N 181, by way of line 282 through back contacts Q 283, brush 270, contact 305, line 306, bar 307, line 308, contacts 304, 304', floor stop switch reset coil 310, line 303, to main 5. As this circuit, by-passing coil V 94 through coil 310 of low resistance, permits increased current flow to coil X 95, the automatic reset switch X operates to separate its contacts X 107, deenergizing coil V 94. Coil V 94 being deenergized, the hall stop switch V will drop out, separating its contacts V 117 and V 113. Separation of contacts V 117 effects the initial slow-down, while separation of contacts V 113 effects the further slow-down and stop of the car in the manner previously described. This increased current, however, is not sufficient to cause coil 310 to reset the floor stop switch. As the automatic reset switch operates, it closes forward contacts X 312 just before it separates back contacts X 107. Thus, just as the circuit is broken for coil V 94, a circuit is established for a holding coil X 313 for the automatic reset switch. When the holding coil circuit is completed, the current flow through reset coil 310 is increased due to the fact that holding coil X 313 is of lower resistance than closing coil X 95 and further to the fact that the current has an additional path around coil X 313 through resistance 314. The increased current is sufficient to cause the reset coil 310 to trip out of the latch permitting contacts 304, 304' to separate, completing the reset operation. The holding coil X 313 serves the additional purpose of giving the floor stop switch sufficient time in which to reset.

It is believed that the operation of the system in response to the pushing of a hall button, so far as the advance or retard of the brushes is concerned, will be obvious from

previous description. In the event of a "short" floor however, with the car at rest at the fourth floor, brush 270 may be in engagement with contact 385. The by-pass, which would be established for coil V 94 with contact 385 "alive," is not complete however because contacts N 181 of the brake resistance switch, included in the by-pass circuit, are open when the motor is at rest. Furthermore, closing coil N 141 is not energized and consequently contacts N 181 are not closed until the starting switch is moved to position II. Thus when the starting switch is moved to position I, the energization of the pawl magnet is effected in the previously described manner so that, when the starting switch is moved on to position II, "selector" switches 132, 133, 134 and 135 will be closed and the motor will start.

As in the case of car button operation response will always be had to hall buttons, regardless of the order in which they were pushed, since the contacts of the floor stop switches, once closed, will be maintained so until tripped out by reset operations. Similarly, during a run from one terminal landing to another, response will be had regardless of the time during the run that the hall button was pushed so long as the "down" hall stop brush 270 with the car traveling in the down direction, or "up" hall stop brush 293 with the car traveling in the up direction, has not passed its corresponding hall stop contact for that floor. As distinguished from car button operation, however, the hall stop contact is not rendered "dead" at the terminal landings so that the call will ultimately be responded to. Since the result of pushing either a car button or a hall button is to prepare a circuit for a corresponding stop contact, it is believed obvious that a car will respond to all calls during a run, regardless of whether due to a car or hall button and regardless of the relative order in which the buttons were pushed.

In order to assure a stop at the second floor, when going up and at the ninth floor when going down, the insulation guarding the selector machine stopping contacts for these floors is cut away in the manner previously described. In order to illustrate the operation, a stop at the second floor will be described. So long as "up" stop brushes 292 and 293 pass below their corresponding second floor stationary contacts 286 and 311, respectively, when the car makes a stop at the bottom floor, the stop at the second floor in response to the car or "up" hall button will be made in the usual manner. However, if for any reason, for example a "short" floor, these brushes do not pass their contacts, due to the fact that the guarding insulation is removed the brushes and contacts will be in engagement. Assuming such a condition with the second floor "up" hall button 472 130

pushed, when the operator moves the starting switch to position II to start the car, contacts N 181 will be closed to complete the bypass for coil V 94. Thus a stop at the second floor is assured. Similarly, with the second floor car button 652 pushed, when the operator moves the starting switch to position II, contacts Z 275 will be closed to complete the short circuit for coil U 93.

Further description of the operation of stopping in response to the pushing of hall buttons will be given along with the description of operation of a group of cars. The operation of the floor signal system will now be described. It has been seen that the floor signal switch operates simultaneously with the floor stop switch in response to the pushing of a hall button. Thus when hall button 295 was pushed, the "down" fourth floor signal switch closed contacts 315, 315' at the same time that the floor stop switch closed contacts 304, 304'. As has been stated, the signal switch also separated its back contacts 300, 300'. Closure of contacts 315, 315' prepared a circuit for "down" fourth floor signal contact 316, rendering it "alive." Assume that the car has started down from the tenth floor and that button 295 has been pushed. The initial circuit to the signal lamp is completed by the leading signal brushes when the car is about forty feet away from the floor called. This distance is more or less arbitrary but has been found in actual practice to give sufficient advance warning for the prospective passenger to note the signal and position himself at the proper elevator door. Thus when the car is forty feet from the fourth floor, leading signal brushes 317 and 318 engage signal contacts 316 and 320 respectively, completing the circuit for the "down" fourth floor signal lamp 321. This circuit may be traced from line 96, by way of line 322 through non-stop switch 323 and automatic non-stop switch contacts 445, by way of line 324 through back contacts Q 325 of the "down" non-interference switch and lamp 321, contact 320, brush 318, connection 326, brush 317, contact 316, line 327, bar 328, by way of line 330 through contacts 315, 315' and reset coil 331, line 303, to main 5. Reset coil 331, as well as reset coil 310, is of low resistance so that the brightness of the signal light will not be affected. The circuit for the lamp is maintained by the succeeding pairs of signal brushes 332-333, 334-335 and 336-337 in the order named, each pair engaging before its preceding pair moves off contacts 316 and 320. With the car stopped at the fourth floor, brushes 336 and 337 will engage contacts 316 and 320, the other brushes having passed beyond, as illustrated in the diagram.

Assuming that the car has completed its stop at the fourth floor, the operator moves the starting switch to position I, and then to

position II starting the car. As has previously been explained, the starting switch in position II causes the operation of a direction switch, in this case direction switch C. Closure of the direction switch auxiliary contacts C 163 completes the circuit for coil O 165 of the signal reset switch. This coil is arranged in series with brake release coil 24, the circuit for which has previously been traced. The signal reset switch operates immediately to close contacts O 338, connecting a resistance 340 of small ohmic value in parallel with lamp 321. This parallel circuit permits sufficient current flow to floor signal switch reset coil 331 to effect the reset operation. Thus contacts 315, 315' separate breaking the circuit for lamp 321. It will be observed that this comparatively late reset operation maintains the signal lighted until the car is actually being started away from the floor. Thus a tardy prospective passenger will be informed that the car is at the floor, affording him an opportunity to "catch" it.

The late reset operation serves another and important purpose in that it prevents reclosure of the floor stop switch until the stop has been fully completed. Prospective passengers sometimes become impatient and push the hall button several times before the car arrives. This might be done just as the car is arriving at the floor and after the floor stop switch has been reset. However, reclosure of the floor stop switch, which would cause a later false stop, is prevented by the fact that back contacts 300, 300' of the floor signal switch remain separated. Thus, even though the floor stop switch is already reset, it cannot be operated again until the corresponding floor signal switch resets to close its back contacts.

As has been seen, closure of contacts C 163 also causes the release of the brake. Contacts 166 are provided on the brake and are arranged to separate as the brake releases. Referring briefly to Figure 39, the brake switch is operated by means of a movable brake magnet arm 580 pivotally mounted on pin 581. Upon energization of brake release coil 24, the brake magnet arm 580 is attracted, operating through rod 582 to cause the switch arm 583 to separate contacts 166. Separation of contacts 166 breaks the circuit for signal reset switch coil O 165, the circuit for brake release coil 24, however, continuing through resistance 341. The signal reset switch now drops out to separate contacts O 338 in preparation for the next starting operation. Contacts O 339 of the signal reset switch are opened and closed along with contacts O 338 but with no effect during down operation of the car due to the separation of "down" non-interference switch contacts P 58.

If no other car or hall buttons are pushed, the car will proceed to the bottom floor and stop in the previously described manner. As

is the case with the bottom floor stop contacts, the bottom floor signal contact 342 is permanently alive. Thus the "up" signal lamp 343 at the bottom floor will be automatically lighted upon the approach of the car. The circuit for lamp 343 is established and maintained in a similar manner as was the circuit for lamp 321 at the fourth floor, the signal brushes engaging in sequence with signal contacts 343 and 344. With the car stopped at the bottom floor, leading brushes 317 and 318 will be in engagement with additional signal contacts 345 and 346. An additional circuit is thus established to lamp 343. This circuit is not affected by the separation of contacts Q 325 in response to the reversal of the "director switch". The circuit for lamp 343, with the "director switch" reversed, may be traced from line 96, line 347, contact 345, brush 317, connection 326, brush 318, contact 346, line 348, line 324, lamp 343, contact 344, brush 335, connection 350, brush 334, contact 342, line 277, line 105, to line 5'. It will be observed that this circuit does not include the trailing signal brushes 336 and 337. This is because contacts 342 and 344 are arranged below the normal floor stop position, as set forth in the description of Figure 11. It is preferred to so arrange contacts 342 and 344 in this manner in order that contacts O 338 of the light reset switch will close in an open circuit, there being no floor signal switch to reset. The light will be extinguished upon up movement of the car as brushes 317 and 318 move off contacts 345 and 346. As signal operation at the top floor is accomplished in the same manner as at the bottom floor, no description is believed necessary.

The system may also be provided with car and dispatcher annunciations in which event the circuit may be arranged so that closure of a hall button causes the completion of a circuit for the corresponding annunciator lamps. A car annunciator is particularly desirable for intermittent service, such as in hotels or in other installations during night operation. Further, it is useful to the operator for any kind of service as it will register the floor where the button was pushed and will indicate the direction in which the prospective passenger desires to go. The dispatcher annunciator is particularly useful where a group of elevators are operating as will be hereinafter set forth.

For the purpose of illustrating the operation of the annunciator system, assume again that the car is at the top floor starting down and that the "down" fourth floor hall button 295 has been pushed. As previously set forth, closure of hall button 295 causes the operation of the "down" fourth floor signal switch to close contacts 315, 315'. Regardless of the position of the signal brushes, closure of contacts 315, 315' immediately completes the circuit for car annunciator

lamp 351 and dispatcher annunciator lamp 352. This circuit may be traced from line 96, by way of line 353 through the parallel circuits comprising the car annunciator cut-out switch 354 and lamp 351 and the dispatcher annunciator cut-out switch 355 and lamp 352, line 327, bar 328, by way of line 330 through contacts 315, 315' and reset coil 331, line 303, to main 5. These lamps will remain lighted until a signal reset operation causes the separation of contacts 315, 315'. The annunciator lamps for the other intermediate floors are controlled in an identical manner for both up and down operation.

It has previously been indicated that no hall buttons, stop switches or signal switches are provided at the top and bottom floors. However, push buttons may be provided at these floors for use in connection with the annunciator system. The operation of the annunciators for the bottom floor will be described, as illustrative of the principle involved. Pushing of the bottom floor annunciator button 356 completes a circuit for the closing coil 357 of the bottom floor annunciator switch. This circuit may be traced from main 4, line 298, by way of line 358 through floor annunciator switch back contacts 359, 359', coil 357, switch 360 and annunciator button 356, line 303, to main 5. The floor annunciator switch, being of the same construction as a floor signal switch, operates in a similar manner to close contacts 361, 361' and to separate contacts 359, 359'. Closure of contacts 361, 361' prepares a circuit for selector machine annunciator contact 362, rendering it "alive", and completes a circuit for the "up" bottom floor car and dispatcher annunciator lamps 363 and 364 respectively. The circuit for these lamps may be traced from line 96, by way of line 353 through the parallel circuits comprising the cut-out switch 354 and lamp 363 and the cut-out switch 355 and lamp 364, line 365, bar 366, by way of line 367 through contacts 361, 361' and reset coil 368, line 303, to main 5. Similar to the operation of the system in the case of the fourth floor annunciator lamps 351 and 352, lamps 363 and 364 will be lighted as soon as contacts 361, 361' close, regardless of the position of the signal brushes, and will remain lighted until the floor annunciator switch is reset. The reset circuit for the floor annunciator switch will be completed by the engagement of the leading "down" signal brushes 317 and 318 and the bottom floor annunciator contacts 362 and 371 respectively. This circuit may be traced from line 96, line 347, line 370, contact 371, brush 318, connection 326, brush 317, contact 362, line 365, bar 366, by way of line 367 through contacts 361, 361' and reset coil 368, line 303, to main 5. In this manner a direct current path, by-passing lamps 363 and 364, is established to reset coil 368. The

reset coil 368 now operates to trip out the latch permitting contacts 361, 361' to separate, completing the reset operation. It is to be noted that the signal reset switch O is not employed for this operation as distinguished from the reset operation for the intermediate floor annunciator lamps. The operation of the annunciator system for the top floor is substantially the same as that for the bottom floor and therefore will not be described. Cut-out switches 354 and 355 are provided to open circuit the car and dispatcher annunciators when their use is not desired. In the event that the dispatcher should have his station at the bottom floor, the annunciator lamp 364 may be omitted. Further description of the operation of the annunciator system will be given along with the description of operation of a group of cars.

Referring now to the whole of Figure 33, the operation of a bank of elevators will be described. It will be understood that the power mains are common to all the elevators. The power and control circuits for the additional elevators will not be shown since they are identical with those illustrated in Figure 32 for elevator No. 1. As has previously been set forth, the floor stop and signal switches are arranged in groups of four, each group for a distinct intermediate floor. These switches, along with their corresponding hall buttons, and the floor annunciator switches along with their push buttons, are common to all the elevators of a bank. The reset circuit for each of these switches leads from an individual bus bar. These bars have been characterized generally in accordance with a floor and circuit. For example, DS 4 indicates that the bar is in the "down" fourth floor stop circuit; UL 2 indicates that the bar is in the "up" second floor lamp or signal circuit; and DA 10 indicates that the bar is in the "down" tenth or top floor annunciator circuit. These bars also are common to all the elevators of a bank. Each elevator has one "up" and one "down" signal lamp for each intermediate floor, a "down" signal lamp for the top floor and an "up" signal lamp for the bottom floor.

Each elevator car is provided with a set of car buttons for the intermediate floors, the sets operating independently. Each car may be provided with an annunciator. The dispatcher annunciator, however, is common to all the elevators.

It is believed that unnecessary duplication will be avoided and that the invention will be sufficiently clear from the illustration of the circuits for the selector machines for two elevators. It is to be understood, however, that the operation of any number of elevators in a group is contemplated. The selector machine wiring diagram for elevator No. 2 is substantially identical with the selector machine wiring diagram for elevator No. 1 and will

not be described in detail except as set forth in the description of operation. The designating letters employed for the various switches, such as U for the car stop switch and P for the down non-interference switch, are used for both selector machine diagrams, differentiation being had by changing the added reference numerals. The wiring diagrams for the two selector machines are arranged for car No. 1 at rest at the fourth floor with its "director switch" in down position, as heretofore set forth, and for car No. 2 at rest at the second floor with its "director switch" (not shown) in up position. Selector machine No. 2 non-interference contacts will therefore be set up for operation, i. e., contacts P 375, P 376 and Q 380 closed and contacts P 377, Q 378 and Q 379 open, as distinguished from the corresponding contacts for selector machine No. 1.

Assume that the "down" third floor hall button 382 has been pushed. "Down" floor stop switch contacts 383, 383' and "down" floor signal switch contacts 384, 384' will therefore be closed. Due to the closure of contacts 383, 383', circuits are prepared for selector machine No. 1 "down" third floor stop contact 385 and for selector machine No. 2 "down" third floor stop contact 386, rendering them "alive." Due to the closure of contacts 384, 384', circuits are prepared for selector machine No. 1 "down" third floor signal contact 387 and selector machine No. 2 "down" third floor signal contact 388. Further, due to closure of contacts 384, 384', the circuits for the "down" third floor dispatcher, car No. 1 and car No. 2 annunciator lamps 390, 391 and 392, respectively, are completed. The circuit prepared for stop contact 385 may be traced from contact 385, line 393, bar 394 (D. S. 3), by way of line 395 through contacts 383, 383' and reset coil 396, line 303, to main 5. The circuit prepared for stop contact 386 may be traced from contact 386, line 397, bar 394, to main 5 as above traced. The circuit prepared for signal contact 387 may be traced from contact 387, line 398, bar 400 (D. L. 3), by way of line 401 through contacts 384, 384' and reset coil 402 line 303, to main 5. The circuit prepared for signal contact 388 may be traced from contact 388, line 403, bar 400, to main 5 as above traced. The circuits for lamps 390 and 391 are believed obvious from annunciator circuits previously traced. The annunciator circuit for lamp 392 may be traced from the power line (not shown) of elevator No. 2, similar to power line 3' of elevator No. 1, line 404, by way of line 405 through cut-out switch 406, lamp 392, line 403, bar 400, to main 5 as previously traced. The annunciator lamps 390, 391 and 392 light immediately. Signal brushes 334 and 335, being already in engagement with the "down" third floor signal contacts 387 and 407,

"down" third floor signal lamp 408 for car No. 1 also lights immediately.

Assume now that the operator for each car moves his starting switch to position II. Car No. 1 will start down and car No. 2 will start up. Engagement of hall stop brush 270 and hall stop contact 385 will cause car No. 1 to slow down and stop in the manner previously described. Also the "down" third floor stop switch will be reset, separating contacts 383, 383'. These circuits will not be traced as they are believed obvious from previous description. The circuit for car No. 1 signal lamp is maintained by the engagement of signal brushes 336 and 337 with signal contacts 387 and 407 respectively. Signal lamp 408 and annunciator lamps 390, 391 and 392 will remain lighted until car No. 1 is again started whereupon the "down" third floor signal switch will be reset in the manner previously described. As has previously been set forth, the reset of a floor signal switch not only breaks the circuit for the signal and annunciator lamps, in this example by separating contacts 384, 384', but also prepares the circuit for its own and the corresponding floor stop switch closing coil by closing its back contacts, here back contacts 409, 409'.

It will be noted that car No. 2, while traveling up, will not respond to the call at the third floor. Engagement of selector machine No. 2 "down" hall stop brush 410 and "live contact" 386 will have no effect as the circuit for brush 410 is open at "up" non-interference contacts Q 378. Similarly, engagement of selector machine No. 2 "up" signal brushes and contacts 388 and 411 will not complete a circuit for car No. 2 third floor "down" signal lamp 412 as the circuit for this lamp is open at "up" non-interference contacts Q 379. As has previously been stated car No. 2 annunciator lamp circuit is broken by separation of floor signal switch contacts 384, 384' after car No. 1 has completed its stop.

If elevator No. 1 car button 653, instead of hall button 382, had been pushed, it will be seen that only car No. 1 will respond since only selector machine No. 1 car stop contact 285 is rendered "alive".

Assume now that the pushing of the "down" third floor hall button 382 occurred after the cars had started and too late for car No. 1 to respond. If no other buttons have been pushed, car No. 2 will proceed to the top floor where it will automatically signal its approach, slow down and stop in the same manner as previously described for car No. 1 at the bottom floor. The "director switch" for elevator car No. 2 will be reversed at the top floor, causing the separation of contacts P 375, P 376 and Q 380 and the closing of contacts P 377, Q 378 and Q 379, preparing the circuits for down car travel. Due to the fact that selector machine No. 2 third floor "down" hall stop contact 386 and signal con-

tact 388 remain "alive" until floor stop switch contacts 383, 383' and floor signal switch contacts 384, 384' separate in response to reset operations, car No. 2 will "pick up" the call on its way down. The circuit for third floor "down" lamp 412 for elevator No. 2 will be completed upon the engagement of leading signal brushes 413 and 414 with contacts 388 and 411 respectively. This circuit may be traced from line 404, by way of line 415 through non-stop switch 416 and automatic non-stop switch contacts 447, by way of line 417 through contacts Q 379, lamp 412, contact 411, brush 414, connection 418, brush 413, contact 388, line 403, to main 5 as previously traced. Car No. 2 will be slowed down and stopped at the third floor in the same manner as described for car No. 1 at an intermediate floor, the engagement of hall stop brush 410 and contact 386 establishing an additional circuit for closing coil X 420 of the automatic reset switch. This circuit may be traced from line 404, line 421, by way of line 422 through contacts V 423 and U 424 of the hall and car stop switches respectively, line 425, coil X 420, contacts X 426, line 427, by way of line 428 through non-stop switch 430, automatic non-stop switch contacts 446 and brake resistance switch contacts N 431, by way of line 432 through back contacts Q 378, brush 410, contact 386, line 397, to main 5 as previously traced. It is not believed that the slow-down, stop and floor stop switch reset operations need further be described in view of similar descriptions for elevator No. 1. Similarly, it is believed that the operations of maintaining the above described lamp circuit and resetting the floor signal switch will be obvious from previous description. Once the call is made, the annunciator lamps 390, 391 and 392 will remain lighted until the "down" third floor signal switch contacts 384, 384' separate, in this example, in response to the floor signal switch reset operation caused by car No. 2. Thus it is seen that response to a call will certainly be made. In fact, the call might be "picked up" by car No. 1 on its next down run if it reaches the third floor ahead of car No. 2.

Assume now that both cars are running in the same direction, for example down, with car No. 1 slightly ahead of car No. 2, and that, before either car reaches the fourth floor, hall button 295 is pushed. Selector machine No. 1 contacts 305 and 316 and selector machine No. 2 contacts 433 and 436 are thus rendered "alive." Advance signal brushes 317 and 318 of selector machine No. 1, upon engagement with contacts 316 and 320, complete the circuit for elevator No. 1 "down" fourth floor signal lamp 321, the circuit being maintained by the brushes which follow in the manner previously described. Then advance signal brushes 413 and 414 of selector machine No. 2, upon engagement

with contacts 433 and 434, complete the circuit for elevator No. 2 "down" fourth floor signal lamp 435. The engagement of hall stop brush 270 and contact 305 of selector machine No. 1 will cause the reset of the "down" fourth floor stop switch, separating contacts 304, 304', and also will cause the slow-down and stop of car No. 1 at the fourth floor. Contacts 304, 304' now being separated, "down" hall stop contact 436 of selector machine No. 2 is no longer "alive." Car No. 2, therefore, passes the fourth floor, the circuit to lamp 435 being broken upon the separation of the trailing signal brushes 437 and 438 and contacts 433 and 434, without effecting the reset of the "down" fourth floor signal switch. The "down" fourth floor signal switch is not reset as car No. 2 passes the fourth floor because its resetting operation is dependent upon the closure of elevator No. 2 signal reset switch O, the closure of which, as previously explained, is dependent upon a stop and restart of a car. The floor signal switch will be reset by the starting operation for car No. 1. Thus with two cars running in the same direction, although the signal lamps for both cars may light, only the car first to arrive at its stopping distance from the landing at which the call was made will stop. By stopping distance is meant the distance from the car to the landing at the instant its stopping operation is initiated. It will be seen from previous description that the stopping distance for each car may vary under certain conditions.

It is preferred to have the hall stop brushes of all selector machines arranged slightly in advance of the corresponding car stop brushes. In this manner, the reset of the floor stop switches is assured even though a hall button and car button for the same floor have been pushed. Assume, for example, that car No. 1 has started down from the top floor with its third floor car button pushed and that a prospective passenger at the third floor pushes "down" hall button 382. The engagement of hall stop brush 270 and contact 385 ahead of the engagement of car stop brush 271 and contact 285 permits the circuit to holding coil X 313 of the automatic reset switch to be completed before a short circuit is established for coil U 93 to effect the separation of contacts U 110 and the consequent deenergization of closing coil X 95. If the circuit for closing coil X 95 is broken too soon, obviously the automatic reset switch cannot operate to complete the circuit for its holding coil X 313. Once the circuit for coil X 313 is established however, the reset operation for the "down" third floor stop switch will be effected because the circuit for this coil is not dependent on contacts U 110 but leads directly from line 96 through contacts X 312. Without a reset op-

eration, the next down car reaching the third floor would make a false stop.

As has previously been indicated, the selector machines, for example selector machine No. 1, may be provided with additional stop control contacts, arranged in columns 448 and 449, and brushes 460 and 461 for effecting local and express operation. A diagram of the preferred arrangement is shown in Figure 34, separate from Figure 33, to 75 more clearly illustrate the principles involved. According to the preferred arrangement, automatic non-stop switches 443 are employed to control the hall stop and signal circuits already described. The automatic non-stop switch contacts, 444 and 445 for elevator No. 1 and 446 and 447 for elevator No. 2, are illustrated in Figure 33 in order to maintain the relationship between the diagrams of the two figures. 85

Referring to Figure 34, the automatic non-stop switch has a closing coil 450 and a reset coil 451. Top floor "up" stop control contact 452 and bottom floor "down" stop control contact 453 are permanently connected to the closing coil 450 in order that the selector machine may operate to signal the approach of the car and stop the car at these two floors in the manner previously described. The circuit for stop control contact 452 may be 90 traced from the contact, line 454, line 455, line 456, coil 450, line 457, to line 5'. Stop control contact 453 is shown as connected directly to line 456. A single pole, double throw switch 458 is arranged in the line from 100 each intermediate floor stop control contact. Each switch 458 is adapted to connect its stop control contact with either closing coil 450 or reset coil 451. The stop control brushes 460 and 461 are arranged to lead the hall stop 105 brushes 293 and 270 respectively, even with the hall stop brushes in their advanced positions. Thus "up" stop control brush 460, for example, will engage a stop control contact before "up" hall stop brush 293 will engage the corresponding hall stop contact. The diagram is arranged for express service between the first and fifth floors and between the seventh and tenth floors in both directions. Thus stop control contact switches 110 458 at the "up" second and eighth floors and "down" ninth and fourth floors are closed in circuits to reset coil 451, and stop control contact switches 458 at the "up" fifth floor and "down" seventh floor are closed in circuits to 115 closing coil 450. All other switches 458 are in open position. Additional forward contacts P 462 and Q 463 may be provided on the non-interference switches P and Q, the function of which will be evident from later 120 description. 125

Referring now to both Figures 34 and 33, assume that car No. 1 is stopping at the bottom floor. As previously explained, the "director switch" will cause the non-interference 130

switches to operate, separating contacts Q 463 and closing contacts P 462. With the car at rest at the bottom floor, depending on the particular installation, brush 460 may be below or in engagement with stop control contacts 464 as illustrated. With the brush and contact in engagement, the circuit for reset coil 451 will be completed and the automatic non-stop switch will operate in the same manner that a floor stop switch resets, to separate contacts 444 and contacts 445. The circuit for the reset coil may be traced from line 4', line 465, switch arm 466 and contact 467 of switch 997, line 468, line 469, contacts P 462, brush 460, contact 464, switch 458, line 470, line 471, coil 451, line 457, to line 5'. So long as contacts 444 and contacts 445 are separated, the car will not respond further to hall buttons either by signalling or stopping. The parts of the system are now in the position illustrated in Figure 34. Thus, even though "up" second floor hall button 472 is pushed, the car will not respond in its upward movement because the circuit for brush 293 is broken at contacts 444 before contacts N 181 are closed in the next starting operation.

Assume now that the car has started in the up direction and that its third floor car button 653, and the "up" fourth and fifth floor hall buttons have been pushed. The "up" fourth and fifth floor stop and signal switches, therefore, will be closed. The car will respond to car buttons and will stop at the third floor, due to the engagement of "up" car stop brush 292 and contact 285, unaffected by the position of the automatic non-stop switch contacts 444 and 445. The car will not stop nor will its approach be signalled at the fourth floor because the circuit to the "up" hall stop brush 293 is open at contacts 444 and the circuit to the signal lamps is open at contacts 445. The fourth floor call will be "picked up," however, by the first up car that reaches the fourth floor running local in that zone. Before car No. 1 reaches the fifth floor, stop control brush 460 engages contact 473 to complete the circuit to closing coil 450. This circuit may be traced from line 4', to brush 460 as above traced, contact 473, switch 458, line 455, line 456, coil 450, line 457, to line 5'. The automatic non-stop switch will now operate to close contacts 444 and contacts 445. Thus the circuit for the "up" fifth floor signal lamp is completed and the slow-down and stop circuit is prepared. Upon engagement of the "up" hall stop brush 293 and the fifth floor hall stop contact, the car will slow down and stop in the manner previously described. So long as contacts 444 and contacts 445 remain closed, there will be response to hall buttons. Thus, if either the sixth or seventh floor "up" hall buttons are pushed, the car will signal and stop at the corresponding floor. Engagement of stop control

brush 460 and contact 474 at the eighth floor will cause the separation of contacts 444 and contacts 445 to prevent further response to the hall buttons until contacts 444 and contacts 445 are again closed. Engagement of the stop control brush 460 and contact 452 at the top floor will cause the closure of contacts 444 and contacts 445 again, permitting the selector machine to complete the signal and car stop circuits. Due to the fact that the "director switch" will now be changed to its down position, contacts Q 463 will be closed and contacts P 462 will be open. It is believed the operation of the selector machine for down car travel will be understood from the above description.

It will be evident that the car may be made express or local for any floor, up or down. For example, by closing switch 458 for the "up" second floor stop control contact on line 470 and the switch 458 for the "down" ninth floor stop control contact 475 on line 456, with the other switches 458 open, the car will run express in the up direction and local in the down direction for all floors.

If it is desired to run local for all floors, both up and down, switch arm 466 is moved into engagement with contact 476 to complete the circuit for closing coil 450, causing the closure of contacts 444 and contacts 445. Due to the fact that these automatic non-stop switch contacts are latched closed, switch arm 466 may then be moved to an off position. Similarly, if it is desired to run express all the way up and all the way down, switch arm 466 is moved into engagement with contact 478, to complete the circuit for reset coil 451, causing the separation of contacts 444 and contacts 445. As before, the switch arm 466 may then be moved to an off position. It will be understood that all the elevators may be arranged for express service operation and that the connections at each selector machine may be varied so that the express zones for each elevator may be different.

As has previously been indicated, the circuits for the floor stop and signal switch closing coils at each floor may be provided with a cut-out switch, for example, switch 302 for the "down" fourth floor coils. These switches are opened whenever it is desired to run all the cars express past the corresponding floors. Thus to run all "down" cars express past the fourth floor, switch 302 is opened, so that the pushing of hall button 295 does not complete the circuit for coils 296 and 301 and contacts 304, 304' and 315, 315' will not be closed. None of the cars, therefore, will respond to this call. It will be observed, however, that the car button circuits for each elevator are not affected by the opening of these cut-out switches.

A floor may be made a regular stop in both directions for any car by connecting the hall stop contacts and the outer signal contacts

for that floor directly to line. For example, if it is desired to have car No. 1 stop regularly in both directions at the third floor, hall stop contacts 385 and 480 and signal contacts 5 387 and 481 will be connected directly to line 5' by way of line 105, as is done with the bottom and top floor hall stop and signal contacts. Car stop contact 285 also may be so connected. If it is desired to have car No. 10 1 stop at the third floor regularly only when traveling down, only contacts 385 and 387 will be connected directly to line 5'. Obviously, when a hall stop and signal contact are connected directly to line, the corresponding 15 circuits to the bus bars are omitted. It will be understood that these connections for the various selector machines may be varied to suit the requirements of the particular installation.

20 It will be obvious from the above description that, where several elevators are installed in a group, connections may be made whereby any car may be caused to run express or local for any desired zone in either direction 25 and other connections may be made whereby any car may be caused to stop regularly at any desired floor in either direction.

20 It has been previously indicated also that the selector machines may be provided with 30 further contacts and brushes for effecting operation of the car position indicator. In Figure 33, selector machine No. 1 car position indicator brush 483 and fourth floor position indicator contact 484 are shown in engagement, completing a circuit for car No. 1 position indicator lamp 485. This circuit may be traced from line 96, line 353, by way of line 486 through indicator cut-out switch 487, by way of line 488 through lamp 485, 40 contact 484, brush 483, line 490, line 491, line 277, line 105, to line 5'. Lamp 485 being lighted indicates that car No. 1 is at the fourth floor. As the car moves up and down, the indicator lamp corresponding to the position 45 of the car will be lighted due to the engagement of brush 483 with the corresponding contact. Selector machine No. 2, car position indicator brush 492 and second floor contact 493 are shown in engagement, completing a circuit for car No. 2 position indicator lamp 494. This circuit may be traced from line 404, line 405, by way of line 495 through indicator cut-out switch 496, by way of line 497 through lamp 494, contact 493, 50 brush 492, lines 498, 499 and 500 to line 501. Line 501 corresponds to line 105 for elevator No. 1. The indicator lamps for elevator No. 2 will light similarly to those for elevator No. 1 depending on the position of the car. The 55 indicator lamps for each elevator may be arranged in a column and the columns suitably arranged on the dispatcher panel. As was the case with the dispatcher annunciator, in the event that the dispatcher should have 60 his station at the bottom floor, the bottom

floor position indicator lamps for all the elevators of a group might be omitted.

65 A dispatcher signal circuit may be provided for each elevator, that for elevator No. 1 leading from line 105, by way of line 502, through dispatcher signal switch 503, resistance 504 and bell 505, to line 96. A similar circuit is illustrated for elevator No. 2 and may be provided for all elevators. The bells or other signals are located in the respective 70 cars while the dispatcher signal switches are located on the dispatcher panel, as illustrated in Figure 1.

75 Thus where a group of elevators are operating, the dispatcher can determine the position of the cars from the car position indicator lamps. When a car reaches the top floor, the dispatcher, at the time he desires the car to start down, may give a prearranged signal by closing the corresponding dispatcher signal switch. If a car gets too far ahead in its 80 relation to other cars during a run, the dispatcher may give another signal for the operator of that car to slow down. The operator of the car so signalled will open the slow speed switch, for example slow speed switch 122 for car No. 1, in the circuit of the operating coils for the second and third accelerating switches, causing the car to slow down. The car will now run at a half speed until 85 further signal is given. In this manner, the cars of a group may be maintained on a schedule. Further, as the dispatcher has full knowledge of all the calls from his annunciator, he may signal the operator of one 90 of the cars to reverse at an intermediate floor and to go back and pick up a call.

95 Assume now that car No. 1 is fully loaded and that its operator desires to run past the remaining floors to a terminal landing or past some of the floors until room is again provided in the car due to discharge of passengers. He may do so by pressing down on the non-stop switch operating lever 614, opening 100 switches 281 and 323. Obviously, in view of the description of operation when contacts 444 and contacts 445 of the automatic non-stop switch were separated, switches 281 and 323 opening the same circuits as contacts 444 and 445 respectively, car No. 1 will not respond further by signal or stop to any of the hall buttons pushed until switches 281 and 110 323 are again closed. The non-stop switches, however, do not change the operation of the car in response to the car buttons. Thus stops 115 are made in the previously described manner for the discharge of passengers. Further, as only the circuits for the hall stop brushes 270 and 293 and elevator No. 1 signal lamps are broken by the opening of switches 281 and 323, the next car running in that direction 120 will "pick up" the hall button calls. If conditions demand it, however, the dispatcher may by-pass the non-stop switches 281 and 323 by closing the non-stop cut-out switches 125 130

506 and 507 provided on his panel. In this manner unwarranted use of the non-stop switches is prevented. The non-stop switches are further useful in maintaining the cars on schedule. For example, the dispatcher, noting from his car position indicator that car No. 1 is behind in its schedule and noting from his annunciator that there are several calls ahead of the car, may give another prearranged signal for its operator to run with the non-stop switch open until further signal is given. The non-stop operation for the other elevators is the same as that for elevator No. 1 and will not be described.

15 Ordinarily, in the event of extra floors, only one elevator is arranged to make the runs due to the fact that such floors are seldom used. Elevator No. 1 has been so illustrated for convenience of description, but it will be understood that other elevators of a group may be so arranged if desired. As car No. 1 arrives at the top floor, the "director switch" will be moved into down position as previously indicated. In order for the car to run 20 to the extra top floor, the operator moves the "director switch", by means of handwheel 688 in the car, back into an up position. As previously indicated, according to the preferred arrangement the "director switch" 25 cannot be moved all the way into full speed up position but is stopped, due to the contour of the hatchway cam, with its segment 70 short of engagement with contact 508. Thus, when the operator moves the car switch to 30 position II, the car will proceed at half speed to the extra floor landing. There the car will be stopped in the manner previously described, the selector machine being provided with car stop contact 509, hall stop contact 510 and extra floor stopping collar 848 for this 35 purpose. Contacts 509 and 510 are permanently "alive", being connected to line 5' by way of line 511, line 491, line 277 and line 105. The "director switch" will be moved 40 again into down position, where, as previously explained, it cannot now be moved back into up position by hand. The car will stop automatically at the top floor as it travels down due to engagement of "down" car stop 45 brush 271 and contact 512, contact 512 being permanently "alive" due to its connection to line 5' by way of line 513, line 491, line 277 and line 105. An additional stopping collar 55 850 is arranged on the selector machine to initiate the final slow-down and stop operations at this floor. Contacts 514 and 515 and extra floor stopping collar 849 are provided for stopping the car at the extreme bottom floor. Any suitable signalling arrangement 60 may be provided for calling the car to these floors, for example push button annunciator arrangements such as described and illustrated for the top and bottom floors.

65 The operator may control the car by means of the handwheel 688 and starting switch for intermediate floor runs. For example, if the car is at the fifth floor with the "director switch" in the down position and it is desired to operate the car in the up direction, the operator may move the "director switch" to 70 up position by means of the handwheel and then start the car in the usual manner. The car may now be stopped by operating the handwheel to move the "director switch" to "neutral" position. Direction switch holding coils C 146 and B 177 are particularly useful in guarding against the effect of sudden movements of the "director switch" to "neutral" position while the main motor is running. Thus for example, even though the circuit for closing coil C 62 is broken by segment 70 during such a movement, direction switch C is held in by coil C 146 until the circuit for this coil is broken by the separation of contacts D 197 of the first accelerating 75 switch. Retarding resistances 516 and 517 are arranged in parallel with coils C 146 and B 177 respectively to insure a sequence of operation between the first accelerating switch and the direction switches. Holding coil N 80 198 controls brake resistance switch N in a similar manner under such operating conditions. If a car is run entirely on the handwheel and starting switch, the car annunciator is particularly useful since the operator, by observing the annunciator lights, may direct the car to the floors called without runs to the terminal floors.

85 Auxiliary motor switches 518 and 519 are provided for use under usual or emergency conditions. Switch 518 in closed position by-passes leveling switch contacts 226, 226' and 227, 227' to complete circuits for auxiliary "down" direction switch coil H 230 and auxiliary speed switch coil K 231 respectively. Switch 519 in closed position similarly 90 by-passes leveling switch contacts 520, 520' and 521, 521' to complete circuits for auxiliary "up" direction switch coil G 260 and coil K 321 respectively. The by-pass circuit 95 for coil H 230 may be traced from line 1', line 68, switch 33b, line 81, coil J 228, by way of line 232 through back contacts G 233 and coil H 230, line 236, line 522, switch 518, by way of line 523 through auxiliary gate contacts 524, line 187, to line 5' as previously traced. The by-pass circuit for coil K 231 through switch 518 may be traced from line 81, line 82, by way of line 234 through coil K 231, line 235, line 525, switch 518, to line 5' as above traced. The by-pass circuits for coils G 260 and K 100 120 125 130 231 through switch 519 are similar to those through switch 518 and will not be traced. Thus if the main motor becomes inoperative or the car is carrying a heavy load, such as a safe, operation may be had on the auxiliary motor by closing switch 518 or 519, depending on the direction desired. Further, these switches may be employed to bring the car to

the floor called in the event that a stop is made outside a leveling zone.

In case of an extreme emergency, such as a fire, when the gate and doors cannot be closed, 5 operation may be had by breaking glass plate 616 in the car operating box and closing emergency cut-out switch 526 to by-pass gate contacts 136, door contacts 137 and door contact sequence relay contacts S 144. Contacts S 144 are by-passed because, with the gate and door contacts open upon the bridging of starting switch contacts 138 in the starting operation, the door contact sequence relay S will operate. As has previously been explained, 15 operation of the door contact sequence relay will separate contacts S 144, preventing the starting of the car under normal operating conditions. Thus if the gate or a door cannot be closed, the operator breaks the glass plate 616, closes emergency 20 cut-out switch 526, permitting the starting of the car. Both coils S 140 and S 142 of the door contact sequence relay will now be energized, permitting contacts S 129 to close so 25 that the car will accelerate in the normal manner.

Safety switch 44 is provided for stopping the car in case of an emergency. Opening this switch breaks the circuit for coil A 41, 30 permitting the main potential switch A to drop out. Thus contacts A 49, A 50 and A 52 separate to break the main motor armature circuit and to cause the application of the brake and contacts A 47 and A 48 close 35 in sequence to connect electrodynamic brake resistances 17 and 18 across the armature, stopping the motor. Opening of any of the "safety switches" included in line 45 or of contacts Y 46 of the fuse protective relay 40 will effect the stopping of the car in the same manner.

The preferred form of fuse protective relay, illustrated in Figure 35, comprises an operating plunger 528 provided with four operating coils Y 530, Y 531, Y 532 and Y 533, 45 each connected across a main line fuse 29 and each capable, when energized, of effecting the operation of the relay. So long as the main line fuses are intact, the operating coils are 50 not energized. If any of the fuses in lines 1', 2', 3' or 5' should fail, however, the corresponding operating coil will be immediately energized to effect the separation of contacts Y 46. No coil is provided across fuse 29 55 in line 4' as steady operation on line 4' cannot be had, that is, line 4' serves merely as a voltage step in acceleration or retardation. A wedge shaped stationary catch 534 is mounted on the control panel. Plunger 528 is 60 provided with spring members 535 and 536 for engaging catch 534 to latch the relay in open position. With the reclosure of contacts Y 46 prevented in this manner, the trouble will be overcome and a new fuse inserted 65 before the latch is released. Thus any danger,

due to a failure of a main line fuse, such as loss of control or damage to the motor, is avoided. It is to be understood that the coils Y 530, Y 531, Y 532 and Y 533 may be arranged to operate separate relays, the contacts of which would all be included in line 45. 70

Mechanical interlocks, referred to in the description of operation, suitable for the proposed main accelerating switches are illustrated in Figures 36 and 37. No attempt is made in these figures to illustrate more than the interlock mechanism as the accelerating switches and their interlocks are fully shown in Figure 31. Referring to Figure 36 where-

in the switches are illustrated in open position, switch arm 538 of switch D is provided with a lug 540, while switch arm 541 of switch E is provided with lug 542, both lugs being arranged for engagement with the interlock 85

cam 543. The cam 543 is secured in any suitable manner, such as by a pin (not shown), to a rod 544. This rod is pivotally mounted by a pin 545 on the switch panel. The cam is provided with an oblique surface 546 adjacent 90

to lug 542 and a slot 547 on the side adjacent to lug 540. Thus switch D must operate before switch E, as when both switches are open, lug 540 is interposed in the path of the deflection of cam 543 preventing it from moving 95

to permit switch E to close. After switch D has closed, switch E can close, lug 543 striking against surface 546 of cam 543, pushing the cam toward switch D so that lug 540 enters slot 547, as shown in Figure 37. When 100

both switches are closed, switch E must open first, as lug 540 is held in slot 547 so long as lug 542 is against the side of the cam. Switch D is thus prevented from opening until after 105 switch E opens. The structure and operation of the interlock between switches E and F is exactly the same and will not be described.

Figure 38 is a simplified representation of a form of leveling switch suitable for operation in the system. This switch, designated 110 as a whole by the numeral 30, is pivotally mounted on a bracket 550 extending from a top corner of the elevator car. The switch comprises a pair of stationary contact arms 551 and 552 and a pair of cooperating mov-

able contact arms 553 and 554. The stationary contact arms 551 and 552 extend oppositely from a frame member 555, being secured to the sides thereof as by means of screws. The movable contact arms 553 and 115

554 also extend oppositely from frame member 555, being pivotally mounted thereon as by means of pins. The stationary arm 551 is provided with a fixed contact 227 in the circuit for the auxiliary speed switch coil K 231 and a movable contact 226 in the circuit for auxiliary "down" direction switch coil H 230. Stationary arm 552 is similarly provided with 120

contacts 521 and 520 for coil K 231 and auxiliary "up" direction switch coil G 260 respec- 125

130

tively. Movable arm 553 is provided with fixed contacts 227' and 226' for engagement with contacts 227 and 226 and movable arm 554 is provided with fixed contacts 521' and 520' for engagement with contacts 521 and 520. Movable contacts 226 and 520 are extended toward contacts 226' and 520', respectively, by means of springs 556 in order that, for example, contacts 226 and 226' will separate after the separation of contacts 227 and 227'.

It is to be understood that suitable insulation is provided for all the contacts so that distinct circuits will be completed by their engagement. Operating rollers 557 and 558, mounted on the ends of movable arms 553 and 554, respectively, co-act with leveling cams 560 and 561, mounted in the hatchway at the various floors, to effect the operation of the leveling switch. It is to be understood that only the rollers are in the direct path of the cams. Frame member 555 is secured to an operating shaft 562 in any suitable manner. This shaft extends through a bearing in bracket 550 to form the pivot for the leveling switch. Secured to the extended portion of the shaft 562 is a lever 564. The lever is operated by leveling switch motor 31, being connected thereto by means of a tape 565 wound on the motor operated drum 566. Stops, for limiting the movement of the lever 564, are formed by the extremities of a slot 567 in motor support 568. Spring 570 forms a bias, normally tending to maintain the lever 564 in the position shown, i. e., the position in which the leveling switch is operative.

In operation, upon energizing the motor 31, lever 564 will be operated to move the leveling switch about its pivot until stopped by the top of slot 567, springs 573 acting to maintain the contacts separated. Rollers 557 and 558 will now be out of the path of the cams, as indicated by dotted lines, rendering the leveling switch inoperative. The switch remains in this position, as the car runs past the various floors, until motor 31 is deenergized during a stopping operation. Assume that the car is traveling in the down direction and that a stop is to be made. Upon deenergization of motor 31, spring 570 operates lever 564 to return the leveling switch to the position with the rollers in the path of the cams. This operation will normally occur in the leveling zone so that, for example, roller 557 will engage the vertical surface 571 of cam 560. In this position, both contacts 226 and 226' and contacts 227 and 227' will be closed, spring 556 for contact 226 being compressed. As the roller moves onto the oblique surface 572 of cam 560, spring 573 will force movable arm 553 away from stationary arm 551, separating contacts 227 and 227'. Contacts 226 and 226', however, are maintained in engagement by spring 556. As has heretofore been explained, contacts 227 and 227' being in the circuit for

closing coil K 231 of the auxiliary speed switch, the auxiliary motor will be slowed down. As the roller 557 moves farther down oblique surface 572 and onto surface 574 of the cam 560, spring 573 forces arm 553 farther away from contact 551 causing the separation of contacts 226 and 226' to effect the stopping of the auxiliary motor in the manner previously explained. Movable arm 553 will be held against further movement by a stop 575 arranged on frame member 555. It is believed that the operation of the leveling switch with the elevator car moving in the up direction or in case of an overrun will be obvious from the above description.

In accordance with the provisions of the patent statutes, the principle of operation of the invention, together with the apparatus now considered to represent the best embodiment thereof, have been described; but it is desired to have it understood that the apparatus shown is only illustrative, and that the invention can be carried out by other means.

What is claimed is:

1. The combination with an elevator car and an electric driving motor therefor of a source of power for the motor, means for discontinuing the supply of power from said source to the motor at a predetermined point in the travel of the car means dependent on the voltage across the motor armature, means dependent on the current in the motor armature circuit, and means controlled conjointly by said voltage dependent means and said current dependent means for determining the speed of the motor and therefore of the car at said predetermined point.

2. In combination, a motor, a source of power for the motor, a device driven by the motor, a brake for the motor, means for applying the brake when the device is at a predetermined distance from a stopping point, and means for partially applying the brake when the device is at a greater distance from said stopping point the additional distance being a function of the load on the motor.

3. In combination, a motor, a source of power for the motor, a device driven by the motor, a brake for the motor, means for applying the brake when the device is at a predetermined distance from the stopping point, and means responsive to the load on the motor for partially applying the brake when the device is at a greater distance from said stopping point.

4. In combination, a motor, a source of power for the motor, a device driven by the motor, a brake for the motor, means for applying the brake when the device is at a predetermined distance from a stopping point, and means dependent on the voltage across the motor armature and the current supplied thereto for causing a partial appli-

cation of the brake when the device is at a greater distance from said stopping point.

5. In combination, a motor, a source of power for said motor, a device driven by the 5 motor, means for interrupting the supply of power by said source to the motor when the device reaches a predetermined point in its movement and means for decreasing the supply of power to the motor when the device 10 reaches a point the distance of which from said predetermined point is a function of the power supplied to said motor.

6. In combination a motor, a source of power for the motor, a device driven by the 15 motor, means for interrupting the supply of power by said source to the motor when the device reaches a predetermined point in its movement, means for decreasing said supply of power when the device reaches a point the 20 distance of which from said predetermined point is determined in accordance with the speed of the device, and means for further decreasing said supply of power when the device reaches a point the distance of which 25 from said predetermined point is a function of the load on the motor.

7. The combination with a motor and an elevator car driven thereby, of a source of current for the motor, a brake for the motor, 30 means for interrupting the supply of current from said source to the motor and for fully applying the brake when the car reaches a predetermined point in its travel, means for initiating a decrease in speed of the motor, 35 before the interruption of the supply of current, at the time that the car arrives at a distance from said point determined in accordance with the speed of the motor, means for causing a further decrease in speed of the 40 motor, before the interruption of the supply of current, at the time that the car arrives at a distance from said point which is a function of the current supplied, and means for partially applying the brake before said full 45 application thereof at the time that the car arrives at a distance from said point which is a function of the current supplied.

In testimony whereof, we have signed our names to this specification.
